UNITED STATES PATENT OFFICE.

WILSON L. CAMPBELL, OF CHICAGO, ILLINOIS, ASSIGNEE, BY MESNE ASSIGNMENTS,
TO AUTOMATIC ELECTRIC INC., OF CHICAGO, ILLINOIS, A CORPORATION OF DELA-
WARE.

AUTOMATIC SWITCHING AND TELEPHONE SYSTEM.

Application filed June 19, 1905. Serial No. 265,955.

To all whom it may concern:

Be it known that I, WILSON L. CAMPBELL, a citizen of the United States of America, and resident of Chicago, Cook County, Illinois, have invented a certain new and useful Improvement in Automatic Switching and Telephone Systems, of which the following is a specification.

My invention relates to automatic telephone systems of that particular type in which any calling subscriber may connect his line with that of any other subscriber by momentarily and successively establishing a number of ground-circuits, so as to transmit to the exchange or central station a number of electrical impulses corresponding to the digits of the number of the called subscriber, these electrical impulses being employed for producing a step-by-step operation on the part of one or more switching machines at the said exchange or central station, whereby the apparatus as a whole is under the control of any calling subscriber for the purpose of picking out and connecting some other subscriber's line with his line, providing, of course, that the called subscriber's line is not busy. More specifically considered, my invention relates to automatic telephone systems of the foregoing general character in which the switching machines are of two kinds—that is, divided into two general classes, one general class being known as "selectors", the other general class being known as "connectors", and the class of "selectors" then being divided into sub-classes, so to speak, according to the size of the exchange, one sub-class being known as "first-selectors", and the other sub-class being known as "second-selectors". As is well known, a "selector" consists of an electrically-propelled and step-by-step-actuated switching machine which may be employed by a calling subscriber for picking out a certain group of trunk-lines, but which ceases in a measure to be under the control of the calling subscriber as soon as the desired group of trunk-lines has been located, and which then proceeds to pick out an idle or non-busy trunk-line, it being understood that, as far as the calling subscriber is concerned, any one of the trunk-lines in such group will serve his purpose. On the other hand, a "connector" is also an electrically-propelled and step-by-step-actuated switch-

ing machine adapted to be employed for picking out a certain group of lines; but in this case, it is a group of subscribers' lines which is picked out, rather than a group of trunk-lines; and, furthermore, a "connector" is also distinguished from a "selector" in this respect,—to-wit, that it is under the control of the calling subscriber throughout its entire operation—that is, it is not only controlled directly by the calling subscriber for that part of its operation during which it picks out the particular group of subscribers' lines, but it then continues under the direct control of the calling subscriber while it is picking out or locating the particular subscriber's line with which the calling subscriber desires to connect his line. There are, of course, and as will hereinafter more fully appear, certain operations which are characteristic of both of these kinds of switches, and which are strictly automatic and not under the control or management, so to speak, of the subscribers. For example, in an automatic telephone system of this character it is essential that the "selectors" be equipped with automatic means for preventing their wipers or switching-arms from stopping on the contacts or terminals which are connected with trunk-lines already in use, and in a "connector" it is essential that automatic means be provided for precluding the possibility of making connection with a subscriber's line which is already in use, or which is in electrical connection with some other line. Again, the releasing of the different switches, while brought about by some act on the part of the calling or the called subscriber, is throughout of a more or less automatic nature, it being common to employ devices and circuits of such character that the mere act on the part of either subscriber, in hanging up his receiver, serves to automatically disconnect the two lines, and to restore all of the switches or switching machines which have been retained in operation between the two subscribers.

Generally stated, the object of my invention is the provision of an improved, simplified and highly efficient automatic telephone system of the foregoing general character.

Special objects of my invention are the provision of an improved construction and

arrangement whereby it will not be necessary to employ the well-known "side-switches" which have heretofore invariably formed a part of each "selector" — that is to say, I provide an improved arrangement whereby "selectors" without "side-switches" may be employed in the same general manner, and with the same general results and methods of operation which characterize the old systems, wherein each "selector" was provided with a "side-switch"; to provide an improved construction and arrangement whereby certain other more or less objectionable features may be dispensed with, as, for example, the so-called "dead resistance" which has always been included in series with the "release-relays" of the "selectors", it having been the practice prior to my invention to connect the "release-relay" of the "first-selector" in series with the dead-resistance-coil of the "second-selector", whereby the two coils are employed in series in the "release-circuit" extending between switches; to provide an improved construction and arrangement whereby an efficient construction and mode of operation, and the desired results may be obtained by simply connecting the "release-magnet" of one "selector" in series with the "release-relay" of another "selector", and whereby each "release-magnet" of the "second-selectors", or of the "connectors", for example, constitutes the required resistance between one terminal of the battery and one terminal of the "release-relay" of another switch, thus giving each "release-magnet" a double function, so to speak, and thereby insuring more economical results than would be obtained by using separate or additional resistance-coils; to provide an improved construction and arrangement whereby the shaft-cam ordinarily employed merely as a stop for limiting the motion of the "side-switch" can be retained in the structure as a whole, notwithstanding the elimination of the "side-switch" from the machine, and employed as a means for opening and closing some switch-springs which constitute a new feature in a switching machine of this general character; to provide certain improved circuits and circuit arrangements, together with certain novel and advantageous combinations, as hereinafter described and claimed; and to provide certain details and features of improvement tending to increase the general efficiency and serviceability of automatic telephone switching apparatus of this particular character.

To the foregoing and other useful ends, my invention consists in matters hereinafter more fully set forth and claimed.

In the accompanying drawings, Fig. 1, in connection with Fig. 2, is a diagrammatic representation of the switching apparatus and circuits involved when a subscriber at a substation A (Fig. 1) has established connection

with subscriber at a sub-station S, designated as #2241.

To the left of line X—X (Fig. 1) is represented that part of the switching apparatus known as the "first-selector" C; between lines X—X and Y—Y is represented the "second-selector" D; between lines Y—Y and Z—Z (Fig. 2) is represented a "connector" E, and to the right of line Z—Z the called subscriber's "first-selector" F. 75

Figs. 3, 4 and 5 are diagrammatic perspective representations of the "first-selector" C, the "second-selector" D, and the "connector" E, together with their respective bank-80 terminals.

As indicated at sub-station A, each subscriber is provided with a telephone having a ringer 1, a receiver 2, and a switch-hook 3 which controls the positions of a number of springs 4, 5 and 6; 7 and 8; 9 and 10; and 85 11, 12 and 13. There is also a transmitter 14, a local battery 15, and an induction-coil 16 with primary and secondary windings 17 and 18, respectively. The calling device is of any approved or suitable design, and is 90 represented by two push-buttons 19 and 20, together with two springs 21 and 22, and three contact-points 23, 24 and 25. A signaling-button 26 closes a circuit through either of two contact-points 27 or 28 by way 95 of an interposed spring 29.

The sub-station is connected with its "first-selector" C by the two "line-conductors" 30 and 31. Referring to the "first-selector", represented in Fig. 3, a so-called "vertical-line-relay" 35 is normally connected to the "vertical-line conductor" 30 of sub-station A. When this relay is energized, it actuates its armature 36, and in this way the position of the springs 37 and 38, relative to two other springs 39 and 40, is controlled or determined. Normally connected with the "rotary-line-conductor" 31 of sub-station A is a so-called "rotary-line-relay" 41, which is also provided with an armature 110 42. This armature is also designed to operate two springs 43 and 39 with respect to two other springs 40 and 37. A so-called "vertical-magnet" 45 is composed of two coils 46 and 47. These coils, when energized, attract their armature 48, which latter is provided with pivots 49 and 50 that support it on the switch-frame. From this armature there projects an arm 51 retained in normal position by a retracting-spring 115 52. An L-shaped piece 53, and a so-called "vertical-pawl" 54, which is also controlled by a retracting-spring 55, are found on this arm. Another operating electro-magnet is the so-called "rotary-magnet" 58 with its two coils 59 and 60, which control the "rotary-armature" 61. This latter armature vibrates about its supporting-pivots 62 and 63 and is normally controlled by a retracting-spring 64. Said armature has attached 120

130

to it a number of arms, whereof the arm 65 is known as the interrupter-arm and engages, at proper times, the so-called interrupter-springs 66 and 67; another is the so-called "rotary-armature-finger" 68 that works in conjunction with the armature of the so-called "private-magnet"; and last the "rotary-arm" 69 supports a so-called "rotary-pawl" 70. Said pawl is subject to the tension of a coiled spring 71; but the office of these arms, etc. will be hereinafter more fully explained. A so-called "release-magnet" 75, for restoring the switch, is also provided with an armature 76, known as the "release-armature". Said armature, like others described, is supported from the usual pivots 77 and 78, and is held normally by a retracting-spring 79. This spring is held in place by a lug 80, and is ordinarily in electric contact with a spring 81, from which latter it separates when the "release-armature" is attracted. In addition, there is attached to this armature a so-called "release-link" 82, the forward end of which latter is provided with an opening 83 that engages with a so-called "double-dog" 84, through a pin 85, when the switch is released. This "double-dog" is equipped with the following details: Two pivots 86 and 87; two locking-arms 88 and 89; and a retracting-spring 90, which latter controls the position of said "double-dog" while the switch is in use. Another magnet 91, known as the "private-magnet", also has an armature 92 which it operates. The usual pivots 93 and 94 support this armature, and it has an arm 95 that operates a number of springs 96, 97, 98 and 99. One of the distinguishing features of a switch of this kind is the shaft 100. This shaft is provided with a set of circular teeth 101 which are traversed by a channel 102 into which normally projects the end of a shaft-rest-arm 103; and with a set of longitudinal teeth 104. The teeth 101 are called the "vertical-teeth", as they are used for giving the shaft a vertical movement, while the teeth 104 are called the "rotary-teeth", as they are used for giving the shaft a rotary movement. On the upper end of said shaft there is a coil-spring 105, one end of which is attached to a normal-post 106. Just below this there is a normal arm 107 which has supervision over a spring 108, the latter usually being in contact with contact-point 109. Near the lower end of the shaft, the "private-wiper" 110 is supported and insulated from said shaft, but within reach of which wiper is the "private-bank" 111. Still lower are the "line-wipers" 112 and 113, which are separated from each other, and from the shaft, by a suitable insulation 114, and opposite which is situated the "line-bank" 115. A cam attachment 116, just below the longitudinal teeth, through

the means of an insulating piece, controls the connection between the so-called cam-springs 117 and 118. An electro-magnet 120, known as the "back-release-relay" has an armature 121 that operates a spring 122 with respect to a second spring 123. A relay 125, known as the "line-switching-relay" is shown, the armature 126 of which controls certain circuits through the medium of a number of springs 127, 128, 129, 75 130, 131 and 132.

The "second-selector" is almost the same as the "first-selector", and is represented in Fig. 4. The "vertical-line-relay" 135, with its armature 136 and "line-relay-springs" 137, 138, 80 139, 140 and 143, and the "rotary-line-relay" 141 with its armature 142, are identical. The "vertical-magnet" 145, the coils 146 and 147 of which control the "vertical-armature" 148, is also the same. In connection with such an armature, the pivots 149 and 150, and the "vertical-arm" 151, have been referred to; and in connection with the "vertical-arm", such parts as the retracting-spring 152, the L-shaped piece 153, the "vertical-pawl" 154 with its retracting-spring 155, have been explained. The "rotary-magnet" 158, and "rotary-magnet-coils" 159 and 160 with their armature 161, are similar to those shown in Fig. 3. This armature also vibrates 90 about its pivots 162 and 163, and is subject to the tension of a retracting-spring 164. It has the familiar arm known as the interrupter-arm 165 which operates the interrupter-springs 166 and 167; the "rotary-armature-finger" 168; and the "rotary-arm" 169, which latter carries the "rotary-pawl" 170 normally under the tension of the pawl-retracting-spring 171. The "release-magnet" 175, the armature 176 of which is supported 100 from the switch-frame by the pivots 177 and 178, restores the "second-selector-switch." A retracting-spring 179, normally engaged with a lug 180, is ordinarily in electric contact with a contact-spring 181, and holds the 110 armature in a position of rest. The "release-link" 182 is also provided with an opening 183 adapted to engage the lug 185 on the "double-dog" 184. The "double-dog" is provided with the usual pivots 186 and 187 115 about which it vibrates; two locking-arms 188 and 189; and a retracting-spring 190. The "private-magnet" is shown at 191. Its armature 192 is usually supported from the "private-magnet-frame" by pivots 193 and 194, and is provided with an arm 195 which controls the so-called "private-springs" 196, 197, 198 and 199. On the shaft 200, the usual circular teeth 201 have a vertical groove 202; the shaft-rest 203, the longitudinal teeth 204, the coil-spring 205, the normal-post 206, and the stop-arm 207 are all familiar elements. On the lower half of the shaft are the "private-wiper" 208, with the corresponding "private-bank-terminal" 209; 120 125 130 135 140 145 150 155 160 165 170 175 180 185 190 195 200 205 206 207 208 209 130

the "line-wipers" 210 and 211, within reach of which is the "line-bank-terminal" 213; and the cam 214 which, in this case, operates three springs 215, 216 and 217 through the medium of an insulating piece. The electro-magnet 220, which is known as the "back-release-magnet", and its armature 221 that controls two springs 222 and 223, are fully shown. The "line-switching-relay" 225, through its armature 226, controls a number of springs 227, 228, 229, 230, 231 and 232.

The "connector" E has a number of parts similar to those of the first and second "selectors" such, for instance, as the "vertical-line-relay" 235 and the "vertical-line-relay-armature" 236; the "line-relay-springs" 237 and 238, 239, 240 and 243; and the "rotary-line-relay" 241 with its armature 242. The "vertical-magnet" 245, with its coils 246 and 247, controls the "vertical-armature" 248, which latter is, as usual, fastened to the switch-frame by the pivots 249 and 250. In an armature of this type, the "vertical-arm" 251, the retracting-spring 252, the L-shaped piece 253, the "vertical-pawl" 254, and the pawl-retracting-spring 255 have already been pointed out. The "rotary-magnet" 258 also has two coils 259 and 260 which, when energized, operate their armature 261 in an oscillatory manner about its pivots 262 and 263, against the tension of a retracting-spring 264. Said armature is, however, only provided with one arm, to-wit, the "rotary-arm" 265. On the forward end of said arm there is attached the usual "rotary-pawl" 266, which is subject to the tension of a retracting-spring 267. The "release-magnet" 268, the armature 269 of which moves about the pivots 270 and 271, attracts said armature against the tension of the retracting-spring 272. The "release-link" 273, which is rigidly fastened to a pin 274, is provided at its forward end with an aperture 275 designed to engage normally with the locking "double-dog" 276 by means of the lug 277. This "double-dog" is the same as that of the first and second "selectors." It is provided, as usual, with pivots 278 and 279 about which it oscillates, with the two locking-arms 280 and 281, and with the retracting-spring 282. The "private-magnet" 283 has an armature 284 which also oscillates about two pivots 285 and 286. Said armature is provided with an arm 287 which is subject to the tension of a retracting-spring 288. This arm is provided with two flexible springs 289 and 290, on the forward ends of which there is an escapement formed by a number of teeth 291, 292, 293 and 294; and a lateral arm 295 which controls four springs 296, 297, 298 and 299. The usual switch-shaft 300 has its circular teeth 301 slotted at 302; has a shaft-rest 303; has the longitudinal teeth 304; has a coil-spring 305 attached to a normal post 306; and has a nor-

mal arm 307 controlling the springs 308 and 309. The "private-wiper" 310 associated with the "private-bank" 311, the "line-wipers" 312 and 313 associated with the "line-bank-terminals" 315, and the cam 316 near the center of the shaft, are all well known. In addition, there is associated with the "connector" an arm 320 known as the "side-switch-arm", the latter being subject to a retracting-spring 321. On this arm there is a lug 322 near one end, and near the other a shaft 323 on which are mounted a number of wipers 324, 325, 326 and 327 which are adapted to engage a number of contact-points 328, 332 and 336; 329, 333 and 337; 330, 334 and 338; and 331, 335 and 339, respectively. Between the shaft supporting these wipers and the lug 322 are the "side-switch-arm-pivots" 340 and 341 and a lateral arm 342. To this latter arm 342 there is pinned another arm 343 which engages the "double-dog" 276 through the medium of another arm 344. The "side-switch-arm", with all its parts, is known as the "side-switch." This "side-switch" may be made to assume either of three positions. In the third position, the right-hand end of the "side-switch-arm" 320 rests against a lug 345. The "connector" has, in addition, two coils 348 and 352 that constitute a "back-release-relay" and the armatures 349 and 353 of which, when depressed, close together the "connector - back - release - springs" 350, 351 and 354. A ringer-relay 358 is provided with an armature 359 through which it operates a number of springs 360, 361, 362, 363, 364 and 365; and there are two condensers 366 and 367 which appear in the talking-circuit. In Fig. 2, the "first-selector" F of the called subscriber is identical in make-up with the "first-selector" C of the calling subscriber. It has the switch-shaft 370, the circular and the longitudinal teeth 371 and 372, respectively; the "private-wiper" 373 and the "line-wipers" 374 and 375; the cam 376 and the cam-springs 377 and 378; and the normal arm 379 which controls the two springs 380 and 381. The "vertical" and the "rotary" "line-relays" 385 and 386 are shown, with the springs they control—387, 388, 389, 390 and 391—as well as the "line-switching-relay-springs" 392, 393, 394, 395, 396 and 397 that are under the control of the "line-switching-relay" 398. Other electro-magnets are the "rotary-magnet" 400, the "release-magnet" 401, the "vertical-magnet" 402 and the "back-release-relay" 403. At the central station there is also a ringer-generator M which provides each "connector" with current for signaling purposes. There is also a busy signaling apparatus H, in connection with which there are two circuit-interrupters 406 and 407; and an induction-coil 408 with primary and secondary windings 409 and 410. Having

thus described the mechanical details, it remains to describe their functions in connection with the circuits of the system.

In the drawings, a battery is represented in a number of places; but it will be understood that this is only for convenience of illustration, there being in reality only one battery with its positive terminal preferably grounded. It may be assumed that the switching apparatus is in its normal condition, as illustrated in Figs. 3, 4 and 5. Now, if a subscriber at sub-station A (Figs. 1 and 2) wishes to establish connection with a subscriber at sub-station S, designated as #2241, he will first remove his receiver from its hook and operate his calling device four times, corresponding with the digits 2, 2, 4 and 1. When the receiver 2 is removed from its hook 3, the latter rises under the tension of a spring (not shown), breaking contact with spring 4 and closing contact between the springs 5 and 6, 7 and 8, and 9 and 10. The closing of the last two places contact-point 25 in direct connection with the ground G through the following circuit: from contact-point 25 to conductors 420 and 421, to springs 9 and 10, and to ground G¹. The subscriber will then proceed to press push-button 19 twice, with the result that spring 21 breaks contact with point 23 each time, and grounds the "vertical-line-conductor" 30 twice by putting it in connection with contact-point 25. The result of grounding this conductor twice, momentarily, is that "vertical-line-relay" 35 of the "first-selector" C is energized twice through the following circuit: from ground G¹ at sub-station A to contact-point 25, to "vertical-line-conductor" 30, to springs 128 and 127, conductor 422, "vertical-line-relay" 35 to conductors 423 and 424 to the non-grounded terminal of battery B, to ground G. Thus energized, said "vertical-line-relay" actuates its armature 36, thereby causing springs 38 and 40 to come into contact twice, causing the "vertical-magnet-coils" 46 and 47 to be energized twice in turn through the following circuit: from ground G² through springs 40 and 38, conductor 425, "vertical-magnet-coils" 46 and 47, conductor 426, springs 81 and 79, conductors 427, 428 and 424 to the non-grounded terminal of battery B, to ground G. Thus energized, the "vertical-magnet" 45 attracts its armature 48 which, by means of the arm 51, causes the "vertical-dog" 54 to engage with the circular teeth 101, raising the shaft two steps. At the first impulse of the armature 48, the L-shaped piece 53 on the arm 51 disengages the "release-link" 82 from the "double-dog" or locking device 84, allowing the arm 88 under the tension of the retracting-spring 90 to engage with the circular teeth, locking the shaft in its raised position. At the second impulse, when the shaft is raised the

second step, the same arm 88 holds the shaft in its second position. After the shaft has been raised two steps, the "private-wiper" 110 and the "line-wipers" 112 and 113 will be found on a level with the first contact of the second row of their respective banks 111 and 115. After this has been accomplished, the subscriber at sub-station A presses the button 20 once, thereby grounding the "rotary-line-conductor" 31 once by bringing spring 22 against grounded contact 25 after the former has broken from contact-point 24. The result is that the "rotary-line-relay" 41 of the "first-selector" C is energized once through the following circuit: from ground G¹, as before, through contact-point 25, spring 22, "rotary-line-conductor" 31, springs 131 and 130, conductor 429, "rotary-line-relay" 41, conductors 423 and 424 to the non-grounded terminal of battery B and to ground G. Thus energized but once, the "rotary-line-relay" 41 actuates its armature 42, bringing springs 43 and 40 together, thereby energizing the "private-magnet" 91 once through the following circuit: from ground G² through springs 40 and 43, conductor 420, "private-magnet" 91, conductors 431 and 426, springs 81 and 79, conductors 427, 428 and 424 to the non-grounded terminal of battery B and to ground G.

Thus energized, the "private-magnet" attracts its armature 92 which, by means of its arm 95, causes springs 97 and 98 to disengage and to momentarily come into contact, respectively, with springs 96 and 99. As soon as springs 96 and 97 come into contact, a circuit is closed through the "rotary-magnet-coils" 59 and 60, as follows: from ground G² through contact-point 109, spring 108, conductor 432, springs 97 and 105 96, springs 67 and 66, through "rotary-magnet-coils" 60 and 59, conductors 428 and 424 to the non-grounded terminal of battery B, to ground G. When the "rotary-magnet" is energized, it attracts its armature 61 which, through the medium of the "rotary-armature-finger" 68, prevents the "private-armature" 92 from at once regaining its normal position, thereby preventing springs 96 and 97 from breaking contact before the desired time. The said armature 61, on being attracted, also causes interrupter-arm 65 to separate the springs 66 and 67, thereby breaking the energizing circuit of the "rotary-magnet" 58. As soon as this occurs, the "rotary-armature" returns to its normal position—due to the strength of the retracting-spring 64—allowing the springs 66 and 67 to re-engage, but not until after the "rotary-armature-finger" 68 has permitted the "private-magnet-armature" 92 to fall back sufficiently, under the tension of the spring 98, to allow springs 97 and 96 to separate. While the interrupter-arm 65 and the "rotary-armature-finger" perform their work,

the "rotary-pawl" 70 on the arm 69 engages with the longitudinal teeth 104 on the shaft, rotating it one step, causing the "private-wiper" 110 to engage with the first contact on the second row of "private-bank" 111, and the "line-wipers" 112 and 113 to engage with the first contact of the second row of the "line-bank" 115. The arm 89 of the "double-dog" 84 locks the shaft in its advanced position by engaging with the longitudinal teeth. Referring to Fig. 1, when the shaft 100 is in its normal position, the cam 116—due to a beveled edge on its upper inner side—permits springs 117 and 118 to maintain, normally, contact with each other, but as soon as said shaft is raised, these springs are separated through the medium of an insulating piece 433. However, as soon as the shaft is rotated, these springs again resume contact, the cam being removed from behind the insulator 433. Referring to Fig. 3, as soon as the shaft is rotated so that the wipers engage the first contact in their respective banks, and after the locking-arm 89 engages with the longitudinal teeth 104, the "rotary-armature" 61 returns to its normal position, allowing the "private-armature" 92 to return likewise, permitting springs 96 and 97 to disengage. At the instant that these two separate, after the cam 116 has been rotated so as to permit the springs 117 and 118 to close contact, the so-called "line-switching-relay" 125 is energized through the following circuit: from ground G^3 through contact-point 109, spring 108, conductors 432 and 435, springs 118 and 117, "line-switching-relay" 125, conductor 436, interrupter-springs 67 and 66, "rotary-magnet-coils" 60 and 59, conductors 428 and 424 to the non-grounded terminal of battery B and to ground G. As soon as this "line-switching-relay" is energized, it attracts its armature 126, causing springs 128 and 131 to break away from springs 127 and 130 and to engage in turn with springs 129 and 132, respectively. In this way, the subscriber's "line-conductors" 30 and 31 are extended to the "line-wipers" 112 and 113, and to a "second-selector-trunk-line" leading from the first contact of the second row of the "line-bank-terminals" 115, as follows: from the "vertical-line-conductor" 30 through springs 128 and 129, conductor 437, "vertical-line-wiper" 112 through trunk-lines similar to trunk-lines 438 and 439 shown leading from the tenth contact of the second row of "line-bank-terminals" 115 to a "second-selector" and back over the "rotary-line-wiper" 113 to conductor 440, springs 132 and 131 back to "rotary-line-conductor" 31. At the same time, a guarding potential is established at the first contact of the second row of the "private-bank" 111, through a circuit that leads to the grounded

terminal of battery B, as soon as the springs 97 and 98 close contact. The circuit is from ground terminal of battery B, to ground G^3 , through springs 109 and 108, conductor 432, springs 97 and 98, conductor 434, "back-release" relay 120, conductor 441, "private-wiper" 110 to the first contact of the second row of "private-bank" 111.

The object of this guarding potential will be hereinafter more fully described. It will be noticed that the "line-switching-relay" 125 is energized through a circuit, in series with the "rotary-magnet" 58; but the latter is of such a design that the current that passes through it by way of the "line-switching-relay" 125 is not sufficiently strong to attract its armature 61. The relay 125 does not energize when the "rotary-magnet" is energized, because it is short-circuited by reason of the "private-springs" 96 and 97 being in contact while the "rotary-magnet" is operated. It may be assumed that the first nine trunks leading from the first nine contacts of the second row of the "line-bank-terminals" 115 are busy at the time the subscriber of sub-station A presses the button 20, after pressing the button 19 twice for the first time. In that case, there will be nine "first-selectors", similar to "first-selector" C, occupying the nine trunks or trunk-lines; the "private-wiper" of each of these "first-selectors" being connected with the ground terminal of battery B in the same manner that "private-wiper" 110 has been shown connected with said grounded terminal. Returning to that part of the operation after subscriber at sub-station A has pressed the button 19 twice, and has raised the shaft 100 two steps, it will be remembered that the push-button 20 was pressed once. The "rotary-line-relay" 41 of the "first-selector" C was thereby energized once, causing the "private-magnet" 91 to be in turn energized, attracting its armature 92 and causing springs 97 and 98 to separate and to engage respectively with springs 96 and 99. The engagement of the upper two—96 and 97—causes the energization of the "rotary-magnet" 58 through a circuit that was described. As soon as the "rotary-magnet" was energized, it attracted its armature 61, detaining the "private-armature" 92 in its depressed position. At the same time, the shaft was rotated one step, bringing the "private-wiper" 110 into engagement with the first contact of the second row of the "private-bank" 111. As has been stated, this contact, as well as the next succeeding eight, are supplied with a guarding potential by switches in some part of the central office, the "private-wipers" of which are engaged with "private-contact-points" connected in multiple. At the instant that the "private-wiper" meets this guarding potential, the "private-magnet" 91 is energized through the follow-

ing circuit: from grounded terminal of battery B to "occupying-switch" and circuit (not shown) to the first contact of the second row of "private-bank" 111 to "private-wiper" 110, conductor 441, "back-release-relay" 120, conductor 434, springs 98 and 99 to "private-magnet" 91, conductors 431 and 426, springs 81 and 79 to conductors 427, 428 and 424 back to the non-grounded terminal of battery B. Thus energized, the "private-magnet" 91 attracts its armature 92, relieving the "rotary-armature-finger" of its guard over said armature, so that even after the interrupter-arm 65 has broken the energizing circuit through the "rotary magnet" 58, by separating springs 66 and 67, and allowing the "rotary-armature" 61 to regain its normal position, the "private-armature" 92 is still held down. In this way, the 20 springs 96 and 97 are retained in contact, so that as soon as springs 66 and 67 re-engage, the armature 61 is again attracted, again rotating the shaft 100 one step through the medium of the "rotary-pawl" 70 and the 25 arm 69. The springs 66 and 67 again being separated, again break the circuit through the "rotary-magnet" 58, and allow the armature again to return to its normal position. This is repeated as many times as the "private-wiper" 110 encounters contact-points having guarding potentials. When the "private-wiper" has been rotated to the ninth contact of the second row of bank 111, the "rotary-armature" is attracted once 30 more, rotating the shaft and the "private-wiper" 110 to the tenth contact. As soon as the "private-wiper" disengages with the ninth contact, the circuit through the "private-magnet" 91 is broken, and the "private-armature" 92 is restored to the care of the "rotary-armature-finger" 68. As soon as the interrupter-arm 65 breaks the contact of springs 66 and 67, the armature 61 returns to its normal position for the last time, 35 permitting the "private-armature" 92 to return with it. The interrupter-springs 66 and 67 again engage, but not until after "private-springs" 96 and 97 have disengaged. The last spring 97 then comes in contact with the spring 98 which in turn 40 has also disengaged from another spring 99.

At the end of this operation, the cam-springs 117 and 118, having engaged in contact after the shaft has been rotated, and as soon as the "private-armature" 92 allows springs 96 and 97 to separate, the "line-switching-relay" 125 is then energized, in the manner already described, thus operating the springs which are controlled through its armature 126, as before. Thus it will be seen that the "first-selector", at the end of its operation, has automatically selected an idle trunk-line, the conductors of which—438 and 439—lead to a "second-selector"; 45 has extended the subscriber's line to the

same in a manner previously described; has established a guarding potential at the tenth contact in the second row of "private-bank" 111, by the closing of springs 97 and 98 as already described; and has disconnected the 70 operating coils that ordinarily rested across the subscriber's line by separating the springs 131 and 128 from springs 130 and 127 at the moment that the "line-switching-relay" 125 is energized. It will be remembered that while the "private-wiper" 110 was passing over contact-points supplied with guarding potential, the "private-magnet" 91 was energized through a circuit that included the "back-release-relay"; but this 75 relay is so designed that under these conditions its magnetic energization is not sufficient to attract the armature 121 against the tension of the spring 122. As soon as the "first-selector" C has extended its line 80 to the "second-selector" D, and a guarding potential is established at the "private-wiper" 110, a circuit is established over the "private-trunk-line" 442 that energizes the "line-switching-relay" 225 at the "second-selector" D through the following circuit: from ground-terminal G of battery B to ground G¹ at "first-selector" C to contact-point 109, spring 108, conductor 432, springs 97 and 98, conductor 434, "back-release-relay" 120, conductor 441, "private-wiper" 110, "private-trunk-conductor" 442, conductor 455 of "second-selector" D, cam-springs 217 and 215, conductor 456, "line-switching-relay" 225, conductors 457, 445 and 446 to the 95 non-grounded terminal of battery B. As soon as the "first-selector" C cuts in on the trunk leading to the "second-selector" D, the "line-switching-relay" 225, being thus energized, attracts its armature 226, causing 100 springs 228 and 231 to disengage from springs 229 and 232, and to engage with springs 227 and 230, respectively. In this way, the "vertical" and "rotary" "line-relays" of said "second-selector" D are bridged 105 across the main "line-conductors" 439 and 438 leading to sub-station A. The subscriber at sub-station A having thus, by the manipulation of his calling device in a manner corresponding to the first digit of the number 2241, which he is calling, connected his line with an idle "second-selector", he then proceeds by again pressing the button 110 twice. This grounds the "vertical-line-conductor" 30 once more, this time energizing the "vertical-line-relay" 135 of the "second-selector" D twice, through the following circuit: from ground G¹ at sub-station A to ground-contact 25 of the calling device, through spring 21, conductor 30, springs 128 and 129, conductor 437, "vertical-line-wiper" 112, trunk-conductor 438, springs 228 and 227, conductor 443, "vertical-line-relay" 135, conductors 444, 445 and 446, to the non-grounded terminal of bat- 115

tery B, and to ground G. Thus energized, the "vertical-line-relay" 135 of the "second-selector" D actuates its armature 136, thereby grounding the spring 138 with ground-spring 140, and in turn energizing the "vertical-magnet" 145 twice through the following circuit: from ground G⁴ to springs 140 and 138, conductor 447, "vertical-magnet-coils" 146 and 147, conductor 448, springs 181 and 179, conductor 449, to the non-grounded terminal of battery B, and to ground G. This "vertical-magnet" operates its armature 148 for the purpose of raising the shaft 200, as in the case of the "first-selector" C. On the first impulse, this armature, through the medium of the L-shaped piece 153, disengages the "release-link" 182 from the "double-dog" or locking-device 184, allowing its arms 188 and 189, under the tension of the retracting-spring 190, to fall against the circular and longitudinal teeth 201 and 204, respectively; the arm 188 locking the shaft in the position to which it is raised by the first step. On the second impulse, the shaft is raised again, and again locked by said arm 188 in the second raised vertical position.

At the end of this operation, the "private-wiper" 208 and the "line-wipers" 210 and 211 will be found on a level with the first contact of the second row of their respective banks 209 and 213. Now, assume that the first nine trunks leading from the first nine contacts of the "private" and "line" banks 209 and 213 are busy, each of the trunk-lines leading from said contacts being engaged by some "second-selector" similar to the "second-selector" D and a guarding potential being established at each one of the first nine "private-contacts" of the second row of "private-bank" 209. The operator at sub-station A now pressing button 20 once, causes the "rotary-line-conductor" 31 to be grounded once, by causing spring 22 to come in contact with grounded spring 25, after having disengaged with contact-point 24. In this way, the "rotary-line-relay" 141 of the "second-selector" D is energized through the following circuit: from ground G¹ at substation A, through the grounded contact 25 of the calling device, spring 22, "line-conductor" 31, springs 131 and 132, conductor 440, "rotary-line-wiper" 113 of the "first-selector" C, "rotary-trunk-conductor" 439, springs 231 and 230, conductor 451, "rotary-line-relay" 141, conductors 444, 445 and 446 to the non-grounded terminal of battery B, to ground G. The "rotary-line-relay", thus energized once, attracts its armature 142, grounding spring 143 on spring 140, and energizing the "private-magnet" 191 through the following circuit: from ground G⁴ to springs 140 and 143, conductors 452 and 453, "private-magnet" 191, conductors 454 and 448, springs 181 and 179,

conductors 449 and 446 to the non-grounded terminal of battery B, and to ground G. The "private-magnet" being thus energized, attracts its armature 192, thereby causing springs 197 and 198 to separate, each engaging in turn with springs 196 and 199, respectively. Spring 197 being grounded at G⁵, as soon as it comes in contact with spring 196 it energizes the "rotary-magnet-coils" 160 and 159 through the following circuit: from ground G⁵ to springs 197 and 196, to interrupter-springs 167 and 166, through "rotary-magnet-coils" 160 and 159, conductors 458 and 448, springs 181 and 179, conductors 449 and 446, to the non-grounded terminal of battery B and to ground G. The "rotary-magnet" 158, being energized, attracts its armature 161. The "rotary-armature-finger" 168 then depresses the "private-armature" 192 and prevents it from regaining its normal position under the tension of springs 196 and 198, thus keeping springs 197 and 196 in contact with each other. The interrupter-finger 165, however, eventually separates springs 166 and 167, thereby opening the energizing circuit of the "rotary-magnet". Meanwhile, the "rotary-pawl" 170 on the arm 169 rotates the shaft 200, so that the "private-wiper" 208 and the "line-wipers" 210 and 211 engage with the first contact of the second row of their respective banks 209 and 213. The locking-arm 189 of the "double-dog" 184, engaging with the rotary teeth, retains the shaft in the advanced position. As soon, however, as the interrupter-springs 166 and 167 are separated by the interrupter-arm 165, as stated, the circuit through the "rotary-magnet" 158 is broken. Said magnet then being de-energized, allows its armature 161 to return to its normal position—due to the force of the retracting-spring 164. Before this, however, at the instant the "private-wiper" 208 engages with the first contact of the second row of the "private-bank" 209, which is supplied with a guarding potential, the "private-magnet" 191 is again energized. In this way, the "private-spring" 196 is held in contact with the grounded "private-spring" 197 while the "rotary-armature" 161 is returning to its normal position. So as soon as the springs 166 and 167 come together, the "rotary-magnet" 158 is again energized. It again attracts its armature, rotating the shaft one more step, thereby placing the "private-wiper" 208 in engagement with the second contact of the second row of the "private-bank", in which position the shaft is maintained by the locking-arm 189 of the "double-dog" 184. Again the interrupter-springs 166 and 167 are separated by the interrupter-arm 165, again de-energizing the "rotary-magnet" 158, the "rotary-armature" 161 falling back once more. This is repeated as often as the "private-wiper" 130

encounters "private-contacts" with guarding potential.

When the shaft has been rotated nine steps, the "private-wiper" 208 will be found engaged with the ninth contact of the second level of the "private-bank". Now, when the "rotary-armature" is again actuated, it rotates the shaft to the tenth step, causing the "private-wiper" to disengage from the ninth contact. In this way, the circuit through the "private-magnet" 191 is broken, and becoming de-energized it gives up its armature 192 to the control of the "rotary-armature-finger" 168. Just at this time, the "rotary-armature" being attracted, the "private-armature" is prevented from returning to its normal position, thus at once preventing springs 196 and 197 from breaking apart too soon. The interrupter-springs 166 and 167 will eventually engage again, but the design is such that this will not occur until after the spring 196 disengages from spring 197. At this point, the "second-selector-wipers" are engaging the trunk-lines that lead from the tenth contacts of the second row of their respective banks. As soon as the shaft is rotated the first step, the cam 214 clears the cam-spring 215, which latter then breaks from spring 217 and engages in turn with spring 216. It might appear that as soon as the cam springs 216 and 217 separate the "line-switching-relay" 225 would be de-energized during rotation, but this is not so, for the energized condition is maintained by current from ground G through springs 197 and 196 to spring 216. After the "rotary-magnet" has ceased to rotate the shaft, and the "private-armature" 192 regained its normal condition, a guarding potential is established at the "private-wiper" 208, and thereby at the "private-contact" with which it is engaged, as well as at all other "private-contacts" connected in multiple. This guarding potential appears as soon as the "private-wiper" is connected with the grounded terminal of battery B, through the following circuit: from "private-wiper" 208 to conductor 458, "back-release-relay" 220, conductor 459, springs 198 and 197, ground G to the grounded terminal G of battery B. At the instant that the "private-armature" 192 regains its normal position and contact between springs 197 and 196 is broken the "line-switching-relay" 225 is de-energized. The armature 226 of this relay, returning to its normal position, disengages springs 231 and 228 from 230 and 227, bringing them in contact with springs 232 and 229, respectively. It is clear that as soon as the "first-selector" C trunks to the "second-selector" D, the latter switch—which normally is off the line—is automatically brought on the line and operated by the manipulation 65 of the calling device corresponding to the

second digit of the number being called. The wipers of said "second-selector" in turn, on seizing an idle trunk, establish a guarding potential at the same. At that instant, also, the "line-switching-relay" is de-energized, thus disconnecting the switch from across the main line, and extending the subscriber's line to a "connector" E through the following path: from "vertical-line-conductor" 30 to springs 128 and 129 of the "first-selector" C, conductor 437, "vertical-line-wiper" 112, "vertical-trunk-conductor" 438, springs 228 and 229, conductor 460, "vertical-line-wiper" 210, "vertical-trunk-conductor" 461 to an idle "connector", back over the "rotary-trunk-conductor" 462, "rotary-line-wiper" 211, conductor 463, springs 232 and 231, "rotary-trunk-conductor" 439, "rotary-line-wiper" 113 of the "first-selector" C, conductor 440, springs 132 and 131 to the "rotary-conductor" 31. The subscriber at sub-station A having thus extended his lines to the "connector", operates his calling device in accordance with the third digit of the number he is calling. He then presses the button 19 four times, grounding the "vertical-line-conductor" 30 four times in a manner already set forth, energizing the "vertical-line-relay" of the "connector" E through a circuit as follows: from ground G¹ at sub-station A to ground-spring 25 of the calling device, to conductor 30, springs 128 and 129 of the "first-selector" C, conductor 437, "vertical-line-wiper" 112, "vertical-trunk-conductor" 438, springs 228 and 229 of the "second-selector" D, conductor 460, "vertical-line-wiper" 210, trunk-conductor 461, "vertical-line-relay" 235 of "connector" E, conductor 464, to the nongrounded terminal of battery B. Being thus energized, the "vertical-line-relay" 235 operates its armature 236 four times, thereby grounding spring 238 on spring 240 four times and energizing, in turn, the "vertical-magnet" 245 through the following circuit: from ground G² through springs 240 and 238, conductor 465, springs 297 and 296, conductor 466, "side-switch-wiper" 324, contact-point 328, "vertical-magnet-coils" 247 and 246, conductor 464, to the non-grounded terminal of battery B. This "vertical-magnet", being energized, attracts its armature 248 four times and, in the same manner as the first and second "selectors", raises the shaft by a step-by-step motion. At the first impulse, the "release-link" 273 is disengaged from the "double-dog" 276 by means of the L-shaped piece 253, thus allowing the locking-arms 280 and 281 of the latter, through the force of the retracting-spring 282, to rest upon the circular and longitudinal teeth 301 and 304, respectively. At the end of the fourth impulse, the wipers are on a level with the first contact of the fourth row of their respective banks; the "private-

wiper" opposite the "private-bank" 311; and the "line-wipers" 312 and 313 opposite the "line-bank-terminals" 315. When the shaft 300 is raised from its first position, 5 springs 308 and 309 controlled by stop-arm 307 are allowed to engage.

The object of this engagement will be hereinafter described. The subscriber at station A now presses button 20 once, 10 grounding the "rotary-line-conductor" in a familiar manner, thereby energizing the "rotary-line-relay" 241 at the "connector" E through a circuit as follows: from ground G¹ at sub-station A to ground-contact 25 at the calling device over "line-conductor" 31 to springs 131 and 132 at the "first-selector" C, conductor 440, "rotary-line-wiper" 113, "rotary-trunk-conductor" 439 to springs 231 and 232 of the "second-selector" D, conductor 463, "rotary-line-wiper" 211, trunk-conductor 462, relay 241, to the non-grounded terminal of battery B. In this way, the armature 242 of said "rotary-line-relay" is attracted once, thus 15 grounding spring 243 with spring 240 once, thereby energizing the "private-magnet" 283 once. The energizing current passes from ground G⁶ through springs 240 and 243, conductor 467, "private-magnet" 283, conductor 464, to the non-grounded terminal of battery B. The "private-magnet", being thus energized, attracts its armature 284 and allows the "side-switch-arm" 320 to disengage with the tooth 291 and to fall against the tooth 292 on its downward stroke. From 20 the latter it disengages on the return of said armature to its normal position. Under the tension of the retracting-spring 321, this "side-switch-arm" is drawn forward until the lug 322 strikes the cam 316. By this motion, the "side-switch-wipers" 324, 325, 326 and 327 are disengaged from the contact-points 328, 329, 330 and 331, with which they normally close, and brought into engagement, in turn, with contact-points 332, 333, 334 and 335. The operator at sub-station A now, for the last time, operates the calling device in accordance with the last digit of the number 2241, pressing button 25 19 once, and grounding the "vertical-conductor" 30, as before. The "vertical-line-relay" 235 is thus again energized through the circuit that has been once described. This "vertical-relay", on attracting its armature once, energizes the "rotary-magnet" 258 once, by causing springs 238 and 240 to close. The circuit is as follows: from ground G⁶ through springs 240 and 238, conductor 465, springs 297 and 296, conductor 466, "side-switch-arm" 324, contact-point 332, coils 259 and 260 of "rotary-magnet" 258, conductor 464, to the non-grounded terminal of battery B. In this way, the armature 261 of the "rotary-magnet" 258 is operated once. The "rotary-pawl" 266, on engaging 30 with the longitudinal teeth 304, rotates the shaft once, and the shaft is held in this rotated position by the locking-arm 281 of the "double-dog" 276. In this way, the "private-wiper" and the "line-wipers" are set on 70 the first contacts of the fourth row of their respective banks, and the cam moving out of the way, the "side-switch-arm" then falls against tooth 293. The operator at sub-station A then grounds the "rotary-trunk-conductor" 31 once, as usual, thereby grounding the "rotary-line-relay" 241 which, on operating its armature, grounds spring 243 on spring 240, thus again exciting the "private-magnet" 283, as before. The "private-magnet", attracting its armature, causes the "side-switch-arm" 320 to disengage from tooth 293 and fall against tooth 294 on its downward stroke. It disengages from the same on its return to normal position and 80 falls against the stop 345. As soon as the "side-switch" is brought into the third position, the "side-switch-wipers" 324, 325, 326 and 327, on disengaging from the contact-points 332, 333, 334 and 335, close in turn 85 with the contact-points 336, 337, 338 and 339. At the instant that the "side-switch-wipers" 326 and 327 engage with the contact-points 338 and 339, the subscriber's line is extended from trunk-conductors 461 and 462 to the "line-wipers" 312 and 313, and thence through the "normal-trunk-conductors" 468 and 469 to the called subscriber's 90 station. The extended circuit is from trunk-conductor 461 to condenser 366 and conductor 470, springs 363 and 364, "side-switch-wiper" 326, contact-point 338, conductor 471, "vertical-line-wiper" 312, conductor 468, to the called subscriber's station and back over the trunk-conductor 469, 95 "rotary-line-wiper" 313, conductor 472, contact-point 339, "side-switch-wiper" 327, springs 361 and 360, conductor 473, condenser 367, to conductor 462. At the same 100 time, a guarding potential is established at the "private-wiper" 310, and thence at the first contact of the fourth row of the "private-bank" 311, as well as at all other multiple contacts, to temporarily prevent any other subscriber from intruding on the 105 called line. This guarding potential reaches the "private-wiper" through the following conductors: from grounded terminal G of battery B, to ground G⁸ at the "side-switch", contact-point 337, "side-switch-wiper" 325, conductor 474, "private-wiper" 310, first contact of the fourth row of "private-bank" 311, and to all other contacts 110 connected in multiple. This connection of the first contact of the fourth row of the "private-bank" 311 with the grounded terminal of the battery B (Fig. 2) causes the "line-switching-relay" of the "first-selector" 115 of the called subscriber to be energized. The circuit formed is from the grounded wiper 120 125 130

310 to the "private-normal-conductor" 517, conductors 518 and 519, cam-springs 378 and 377, "line-switching-relay" 398 of the called subscriber's "first-selector" F, 5 through the winding of the "rotary-magnet" 400 to conductors 520 and 521, to the non-grounded terminal of battery B, and to ground G. As soon as the armature of this "line-switching-relay" is attracted, it causes 10 springs 396 and 393 to separate from springs 397 and 394. The separation of these springs removes a bridge composed of the "rotary" and "vertical" "line-relays" 386 and 385 of the "first-selector" F. This 15 bridge is normally closed across the "line-conductors" 489 and 479 as follows: from conductor 489 through springs 393 and 394, "rotary-line-relay" 386, "vertical-line-relay" 385, springs 397 and 396, and through the 20 "vertical-line-conductor" 479. It is desirable to remove this bridge connection, so that there may be no danger, when the ringing current is sent over the called subscriber's line, of the "line-relays" being energized, as this might interfere with the 25 established connection. The removal of this bridge is also desirable for the reason that any bridge across a talking line-circuit should be removed in order that no part of 30 the voice-currents be uselessly side-tracked or lost. As will later on appear, the conductors 479 and 489 form part of the talking-circuit when the subscribers begin to communicate. The calling subscriber, having 35 established connection with subscriber #2241 in the manner explained, is now ready to ring the bell at the called station. This is done by pressing the button 26 at sub-station A, which causes spring 29 to 40 break from contact-point 27 and engage with contact-point 28, thereby grounding the "vertical-line-conductor" 30 through the following circuit: from ground G¹ through springs 10 and 9 to contact-point 28, springs 45 29, 6 and 5, through contact-point 23, spring 21 to the "vertical-line-conductor" 30, thence through a circuit already described, through the "vertical-line-relay" 235 of the "connector" E to the non-grounded terminal 50 of the battery B. In this way, the "vertical-line-relay" actuates its armature, causing the ringer-relay 358 to be energized. The circuit is from ground G⁶ to springs 240 and 238, conductor 465, springs 297 and 296, conductor 466, "side-switch-wiper" 324, contact-point 336, conductor 475; ringer-relay 358, conductor 476, conductor 464, and to the non-grounded terminal of the battery B. Thus energized, the ringer-relay attracts its armature 359, thus causing springs 361 and 364, respectively, to break from springs 360 and 363, and to engage in turn with springs 362 and 365. It is evident that the first two springs constitute the terminals of the called subscriber's line, while springs 360 and 363 60 constitute the terminals of the calling subscriber's line, the springs 362 and 365 being the terminals of a dynamo M. Therefore, the function of the ringer-relay is to disconnect the called line from the line calling, 70 and to throw it across the terminals of the dynamo M, which latter then rings the bell of the called station through the following conductors: (See Fig. 2.) From generator M to brush 477, conductor 478, springs 365 75 and 364, "side-switch-wiper" 326, conductor 471, "vertical-wiper" 312, "normal-trunk-conductor" 468, "vertical-line-conductor" 479, spring 480, contact-point 481, conductor 482, switch-hook 483, spring 484, ringer 485, conductor 486 contact-point 487, spring 488, "rotary-line-conductor" 489, "normal-conductor" 469, "rotary-wiper" 313, conductor 472, contact-point 339, "side-switch-wiper" 327, springs 361 and 362, conductor 490 to 80 the brush 491 and back to the dynamo M. The bell at sub-station #2241 will now ring as long as the calling subscriber continues to press his signaling-button 26, or until the called subscriber removes his receiver from 85 its hook. As soon, however, as the signaling-button 26 is released, contact is broken between spring 29 and contact-point 28, thereby allowing the "vertical-line-relay" at 90 "connector" E to be de-energized, and in 95 turn the ringer-relay 358. This will restore the connection between the terminals of the called subscriber's line and the terminals of the calling subscriber's line.

As soon as the called subscriber removes 100 his receiver 492 from its hook, the ringing circuit spring 484 breaks contact with the switch-hook 483, thereby breaking the ringing circuit, and a moment later causing the following springs to close: 493 with 494; 495 with 496; and 497 with 498; and placing the "line-circuit" in final condition for talking. The closing of the springs 495 and 493 closes a local circuit at sub-station S 105 from the battery 499, through the transmitter 500 and the primary winding 501 of induction-coil 502, as follows: from battery 499 to transmitter 500, springs 496 and 495, primary coil 501 and back to battery 499. Talking current being thus supplied, when 110 the subscriber at sub-station S speaks into his transmitter 500, the resistance of the local circuit just described is varied, thereby causing the local current to vary, and to induce in turn currents in the secondary winding 503 of the induction-coil 502, in a well-known manner. These induced currents reach the receiver of the calling subscriber through the secondary winding 503 115 of the induction-coil 502, conductor 504, receiver 492, conductor 505, contact-point 487, spring 488, "rotary-line-conductor" 489, trunk-conductor 469, "rotary-line-wiper" 313 of "connector" E, conductor 472, contact-point 339, "side-switch-wiper" 327, ringer- 120 125 120

relay-springs 361 and 360, conductor 473, condenser 367, "rotary-trunk-conductor" 462, "rotary-line-wiper" 211 of the "second-selector" D, conductor 463, "line-switching-relay-springs" 232 and 231, "rotary-trunk-conductor" 439, "rotary-line-wiper" 113 of the "first-selector" C, conductor 440, "line-switching-relay-springs" 132 and 131, "rotary-line-conductor" 31, spring 22, contact-point 24, conductor 505, receiver 2, conductor 506, secondary winding 18 of induction-coil 16, contact-point 27, springs 29, 6 and 5, contact-point 23, spring 21, "vertical-line-conductor" 30, "line-switching-relay-springs" 128 and 129 of the "first-selector" C, conductor 437, "vertical-line-wiper" 112, "vertical-trunk-conductor" 438, "line-switching-relay-springs" 228 and 229 of the "second-selector" D, conductor 460, "vertical-line-wiper" 210, "vertical-trunk-conductor" 461, condenser 366 of the "connector" E, conductor 470, ringer-relay-springs 363 and 364, "side-switch-wiper" 326, contact-point 338, conductor 471, "vertical-line-wiper" 312, "vertical-normal conductor" 468, "vertical-line-conductor" 479, spring 480, contact-point 481, conductor 482, springs 493, 494 and 507, and contact-point 508 through the secondary winding 503 of the induction-coil 502.

30 In like manner, when the subscriber at station A speaks into his transmitter, the voice vibrations will be reproduced at the receiver 492 through the same circuit just described. The vibrations set up in the transmitter 14 affect the local circuit of the battery 15, which induces currents in the secondary winding 18. After the conversation has been completed, the switches may be released or restored to their normal positions by the subscriber at sub-station A in replacing his receiver on its hook. This causes the arm 509 on the hook 3, on its downward course, to momentarily engage spring 11, pressing it forward toward spring 12, so that springs 11, 12, and 13 will be momentarily and simultaneously brought into contact. This causes the "vertical" and "rotary" "line-conductors" 30 and 31 to be momentarily grounded as follows: from ground G¹ through springs 10 and 9, conductor 421, springs 13, 12 and 11, conductors 510 and 511, contact-points 23 and 24, springs 21 and 22 to the line. The grounding of the "line-conductors" causes the "rotary" and "vertical" "line-relays" 235 and 241 at the "connector" E to momentarily attract their armatures 236 and 242, at the same time. In this way, springs 237 and 239 are brought into contact, thereby energizing the "release-magnet" 268 of said "connector", and also the "back-release-relay" of the "second-selector" D, as follows: from ground G⁵ at the "second-selector" D through springs 197 and 198, conductor 459, "back-release-relay" 220, conductor 458, 65 "private-wiper" 208, release trunk 512, springs 237 and 239 of the "connector" E, conductors 513 and 514, "release-magnet" 268, conductors 515 and 464 to the non-grounded terminal of the battery B, and to ground G. Thus energized, the "release-magnet" attracts its armature 269 with a sudden jerk, kicking the "double-dog" 276 inwardly so that the aperture 275 of the "release-link" 273 falls over the lug 277, thus holding the locking-arms 280 and 281 away from the circular and longitudinal teeth 301 and 304. The shaft 300 is thus left to the action of the coil-spring 305, which rotates it upon the shaft-rest 303 until the stop-arm 307 strikes the stop-post 306, at which instant the rest 303 disengages from the circular teeth by re-entering the channel 302 which traverses these teeth. The shaft then drops to its lowest position under the force of gravity, the arm 307 causing the spring 308 to separate from the contact-point 309. When the "double-dog" is thrust inwardly by the "release-armature", its arm 344 drives the link 343 before it, causing the "side-switch" to rotate about the pivots 340 and 341 against the pull of the retracting-spring 321, and causing the "side-switch-arm" to return to its first position. The "side-switch-wiper" 325, on disengaging from the "side-switch-contact-point" 337, removes guarding potential from the first contact of the fourth row of the "private-bank" 311, which causes the de-energizing of the "line-switching-relay" 398 of the called "first-selector" F. In this way, the normally bridged "line-relays" 100 that were removed from the line at the instant the "connector" established connection are restored to the called line.

As was stated, the "back-release-relay" 220 of the "second-selector" D is energized simultaneously with the "release-magnet" 268 of the "connector" E, it being in the same circuit; so that at the same time that the "connector-release-magnet" attracts its armature, the "back-release-relay" 220 also attracts its armature 221, causing the energization of the "second-selector-release-magnet" 175, and of the "back-release-relay" 120 of the "first-selector" C. In this way, the "back-release-relay-springs" 115 222 and 223 are brought into contact, and the energizing circuit is as follows: from ground G³ at the "first-selector" C through springs 109 and 108, conductor 432, springs 97 and 98, conductor 434, "back-release-relay" 120, conductor 441, "private-wiper" 110, "release-trunk" 442, conductor 514, springs 223 and 222, conductor 515, "release-magnet" 175, conductors 449 and 446, to the non-grounded terminal of battery B, and to ground G. Thus energized, the "release-magnet" of the "second-selector" D, attracting its armature 176, thrusts the "release-link" 182 sufficiently forward, so that the aperture 183 in the forward part 130

of the said link catches the "double-dog" 184 by means of the lug 185. The "double-dog" is then rotated in such a manner upon the pivots 186 and 187, when the "release-magnet" becomes de-energized, as to draw the locking-arms 188 and 189 away from the circular and longitudinal teeth on the shaft 200, leaving said shaft to the influence or action of the coil-spring 205. This spring 10 rotates the shaft back on the shaft-rest 203 until the stop-arm 207 strikes the stop-post 206. At this juncture, the shaft-rest 203 disengages from the circular teeth and enters the channel 202, and allows the shaft of its 15 own weight to fall to its restored position. At about the same time that the stop-arm strikes the stop-post, or "normal post", as it is called, the cam 214 causes the cam-spring 215 to separate from spring 216 and 20 to resume its normal connection with the spring 217. The "back-release-relay" 120 of the "first-selector" C being also energized, as stated, attracts its armature 121, in turn energizing the "release-magnet" 75 of the 25 "first-selector" C. In this way, the springs 122 and 123 are brought into contact, and the "first-selector-release-magnet" is energized as follows: from ground G³ through springs 109 and 108, springs 123 and 122, 30 conductor 516, "release-magnet" 75, conductors 427, 428 and 424, to the non-grounded terminal of the battery B, and to ground G. Being thus energized, the "release-magnet" 75 attracts its armature 76, which causes 35 the "release-link" 82 to take hold of the "double-dog" 84, just as was the case in the "second-selector". The "release-magnet", on being de-energized, restores its armature. The "double-dog" is then drawn away from 40 the circular and longitudinal teeth, leaving the shaft to the tension of the coiled spring 105, which restores it to its normal position. Just about the time that the stop-arm 107 strikes the stop-post 106, the cam 116 separates the cam-springs 117 and 118, thus 45 breaking the charged or energized circuit of the "line-switching-relay" 125, and restoring it also to its normal position. The springs 131 and 128 then return into contact with the springs 130 and 127, respectively. Thus, it will be seen that at the instant the 50 switch-hook at sub-station A closes the "release-springs" 11, 12 and 13 into contact, the energization of the "rotary" and "vertical" "line-relays" at the "connector" E, by closing contact between the springs 237 and 239, causes the simultaneous energization of the "connector-release-magnet" 268, and of the "second - selector - back - release - relay" 220. 55 The "back-release-relay" in turn, by attracting its armature, causes the energization of the "release-magnet" of the "second-selector" D, and of the "back-release-relay" of the "first-selector" C, which last relay by 60 attracting its armature energizes the "re- lease-magnet" of the "first-selector" C. All of these electro-magnets will remain energized as long as the "release-springs" at sub-station A remain in contact. The release mechanism of the "connector" differs 70 from the release mechanism of the first and second "selectors" to this extent,—that in the "connector" the "release-armature", on being attracted, by a thrust causes the release of the "connector" at once. The release mechanism of the "second-selector", as well as that of the "first-selector", however, does not restore the switch until after the "release-magnet" resigns control of its armature, and this occurs at the instant that the 80 switch-hook at the releasing sub-station has fallen low enough to allow the "release-springs" to disengage. At that instant, the "vertical" and "rotary" "line-relays" at the "connector" release their armatures, thereby 85 allowing the springs 237 and 239 to separate and break the circuit through the "connector-release-magnet" and the "second-selector-back-release-relay", which relay at 90 this point restores its armature. 95

The restoration of the "back-release-relay-armature" of the "second-selector" D allows the springs 222 and 223 in turn to disengage, thereby permitting the de-energization of the "release-magnet" of the "second-selector" D and of the "back-release-relay" of the "first-selector" C. These last two electro-magnets at once restore their armatures. The restoration of the "second-selector-release-armature" results in the restoration of 100 the "second-selector", as described. The restoration of the armature of the "first-selector-back-release-relay" results in the de-energizing of the "release-magnet" of the "first-selector" C which latter relay, on restoring its armature, releases the switch in 105 the manner explained. After the calling subscriber has released all the switches by the restoration of his receiver, the called subscriber restores his receiver. In the same manner, the "release-springs" 522, 523 and 524 of his sub-station close in momentary contact, simultaneously grounding the conductors of his line from ground G¹¹ through 110 springs 498 and 497, conductor 525, springs 522, 523 and 524, contact-points 487 and 481, springs 488 and 480 to the "line-conductors" 115 489 and 479. The grounding of these conductors results in the energizing of the "vertical" and "rotary" "line-relays" of the "first-selector" F (Fig. 2). As this "first-selector" F is similar to the "first-selector" C, referring to the latter (Fig. 3), the grounding of these "line-conductors" has 120 the same effect as if the "vertical" and "rotary" "line-relays" 35 and 41 were energized. Thus energized, these relays attract their armatures, thereby bringing the springs 37 and 39 into contact, which would energize 125 the "release-magnet" 75 through the follow- 130

ing conductors: from ground G^2 through springs 37 and 39, conductor 516, "release-magnet" 75, conductors 427, 428 and 424, to the non-grounded terminal of the battery B, and to ground G. Thus energized, the "release-magnet" would attract its armature 76, separating springs 79 and 81 on the back of said armature. As this switch is already released, this operation of the "release-magnet" has no effect of importance. The separation of the springs 79 and 81, referred to, is designed to prevent the "vertical" and "private" magnets 45 and 91 from being energized when the springs 38 and 43 are grounded on spring 40, at the time the "line-relays" are magnetized. It has been shown that the circuits of the "vertical" and "private" magnets include the springs referred to on the back of the "release-armature." It is evident that since the "line-switching-relay" 398 of the "first-selector" F is energized while the "connector" E is set on the line leading to the sub-station #2241, the subscriber at said station cannot make a call until the "connector" E is released. Of course, this is due to the fact that the "line-switching-relay-springs" 393 and 396 are separated from the neighboring springs 394 and 397. Therefore, special provision has been made that a called subscriber may be able to release the switches that take part in maintaining a connection between a calling subscriber and his own line, in case the former should neglect to restore said switches after their use. For instance, if the subscriber at station A neglects to release after he is through talking, and the called subscriber should wish to make a call, the latter will pull down the switch-hook 483 and thereby ground his line-conductors 479 and 489. As the switch-hook travels downwardly, the spring 524 comes into contact with the spring 523, thereby grounding the "vertical-line-conductor" 479 by way of ground G^{11} , contact-points 498 and 497, conductor 525, release-springs 524 and 523, contact-point 481, and spring 480. The result is that the "back-release-relay" 348 becomes magnetized. The path followed by the current is from ground G^{11} to the "vertical-line-conductor" 479, "normal-trunk-conductor" 468, "side-switch-wiper" 326, "line-switching-relay-springs" 364 and 363, conductor 470, "back-release-relay" 348, conductor 464 to the non-grounded terminal of battery B and to ground G. The relay 348 being magnetized, the armature 349 presses the grounded spring 350 against the spring 351. An energizing circuit is thereby closed through the "rotary-line-relay" 241, and through the "vertical-line-relay" 235. The path of the current through the former relay is from ground G^7 through the springs 350 and 351, conductor 351, "rotary-line-relay" 241, conductor 464 to the non-grounded terminal of battery B and to ground G. The path of the current through the "vertical-line-relay" 235 extends from ground G^7 through the "back-release-relay-springs" just described, over the "rotary-trunk-conductor" 462, "rotary-line-wiper" 211 of the "second-selector" D, conductor 463, "line-switching-relay-springs" 232 and 231, "rotary-trunk-conductor" 439, "rotary-line-wiper" 113 of the "first-selector" C, conductor 440, "line-switching-relay-springs" 132 and 131, "rotary-line-conductor" 31, spring 22, contact-point 24, conductor 505, receiver 2, secondary winding 18 of induction-coil 16, contact-point 27, spring 29, springs 6 and 5, contact-point 23, spring 21, "vertical-line-conductor" 30, "line-switching-relay-springs" 128 and 129, conductor 437, "vertical-line-wiper" 112, "vertical-trunk-conductor" 438, "line-switching-relay-springs" 228 and 229 of the "second-selector" D, conductor 460, "vertical-line-wiper" 210, "vertical-trunk-conductor" 461, "vertical-line-relay" 235, conductor 464 to the non-grounded terminal of battery B and to ground G. The "line-relays" of the "connector" being thus energized simultaneously, their armatures close the open contact between the springs 239 and 237, and thereby complete a circuit through the "release-magnet" 268 of the "connector" E and through the "back-release-relay" 220 of the "second-selector" D, as has already been described. The result is that not only the "connector" but the "second-selector", and eventually the "first-selector", are released. However, if for any reason the circuit between the calling sub-station A and the "connector" has been opened—for instance, by the blowing of a fuse—the "connector" E will still be released, for as the switch-hook 483 continues down, the three release-springs 522, 523 and 524 are flexed into contact, the "rotary-line-conductor" 489 will also be grounded, and the "back-release-relay" 352 will become magnetized at the same time with the "back-release-relay" 348. The path the current will take through the said relay 352 is from ground G^{11} through conductor 525, release-springs 524, 523 and 522, contact-point 487, spring 488, "rotary-line-conductor" 489, "normal-trunk-conductor" 469, "rotary-line-wiper" 313 of "connector" E, conductor 472, contact-point 339, "side-switch-wiper" 327, "ringer-relay-springs" 361 and 360, conductor 473, "back-release-relay" 352, conductor 464 to the non-grounded terminal of battery B and to ground G. The armatures 349 and 353 being attracted at the same time, the "back-release-relay-springs" 350, 351 and 354 are brought into contact and the "connector-release-magnet" 268 will be energized through a circuit beginning with ground G^7 and thence through springs 350, 351 and 354, conductors 513 and 514, "release-magnet" 268, conductors 515 and 464 to the non-grounded terminal of battery B and to ground G.

grounded terminal of battery B and to ground G. In this last case the "release-magnet" will be energized alone and not in series with the "back-release-relay" of the "second-selector." The "release-magnet" being thus energized, the release mechanism of the "connector" is operated and the shaft restored to its normal position. As soon as the "connector" is released in either of the above cases, the "private-wiper" 310 breaks with the first contact of the fourth level of the "private-bank" 311, thereby destroying the energizing circuit through the "line-switching-relay" 398 of the "first-selector" F. The armature of this relay will return to its normal position, as well as the "line-switching-relay-springs." The "line-relays" 385 and 386 being then restored to the line of sub-station #2241, the subscriber may then proceed to make his call.

Having once described the process by which one subscriber establishes connection with another, and the method of releasing the switches, it remains to assume a case where a calling subscriber attempts to call a busy line. A line may be busy in either of two ways, viz, by being called or by making a call. Suppose some one is connected with sub-station #2241 at the time a subscriber at sub-station A attempts to connect with the line of this sub-station #2241. There will be a "connector" similar to "connector" E, the wipers of which are set on the first contacts of the fourth row of their respective banks, and the "side-switch" of which is in the third position. A guarding potential exists, therefore, at this "private-contact". Now, this guarding potential extends not only to the "private-contact-point" with which the occupied switch is connected, but to all others which are in multiple. Therefore, every avenue through which a "connector" could establish connection with subscriber #2241 is guarded. Now return to that stage of the call where the subscriber at sub-station A, in calling the subscriber at sub-station #2241, had operated his switch, so that the "first-selector" C, having been raised two steps and cut-in ten steps, had trunked to the "second-selector" D; and where the "second-selector" D, having been raised two steps and cut-in or rotated ten steps, had trunked to the "connector" E; and last, where the "connector" E had been raised four steps and cut-in one step, and the "side-switch" had been brought to the second position. The "private-wiper", under these conditions, is in engagement with the first contact of the fourth level of its bank, and the "private-magnet-spring" 298 is in direct connection with the grounded terminal of the battery B as follows: from ground G through the occupied switch and a circuit (not shown) to the first contact

311, the "private-wiper" 310, the conductor 474, "side-switch-wiper" 325, contact-point 333 to spring 298. Now, as soon as the subscriber at sub-station A presses button 20 for the last time, so as to complete the connection, he grounds the "rotary-line-conductor" 31 in a well-known manner, thereby energizing the "rotary-relay" of the "connector" E which, in turn, by the actuation of its armature, energizes the "private-magnet" 283. As soon as the "private-magnet" attracts its armature 284, the arm 295 closes contact between the springs 298 and 299, at once energizing the "release-magnet" 268. This releases the "connector" in a well-known manner. The energization of the "release-magnet" occurs through the following circuit: from the grounded spring 298 (which was pointed out) through spring 299, conductors 525 and 514, "release-magnet" 268, conductors 515 and 464, to the non-grounded terminal of the battery B, and to ground G. The calling subscriber, thinking that he has established connection, will press the signaling-button 26, grounding the "vertical-line-conductor" 30, thereby again energizing the "vertical-line-relay" at the "connector". This relay, on attracting its armature, closes contact between springs 238 and 240; but by this time, instead of operating the ringer-relay, the "side-switch" being in the first position, the "vertical-magnet" 245 is energized, causing the shaft to be raised. As soon as this occurs, springs 308 and 309 close, thereby placing a busy signal apparatus across the line, which causes a buzzing sound to be heard by the calling subscriber at his receiver 2. This busy signal apparatus is represented at H (Fig. 2) with one conductor-terminal 526 leading to the non-grounded terminal of the battery B, while the other terminal 527 leads to contact 309. This busy signaling machine may be of any suitable, known or approved type, and connects with the calling subscriber's receiver through conductor-terminal 527 through contact 309, spring 308, "side-switch-contact-point" 331, "side-switch-wiper" 327, ringer-relay-springs 361 and 360, conductor 473, condenser 367, "rotary-trunk-conductor" 462, "rotary-line-wiper" 211 of the "second-selector" D, conductor 463, "line-switching-relay-springs" 232 and 231, "rotary-trunk-conductor" 439, "rotary-line-wiper" 113 of the "first-selector" C, conductor 440, "line-switching-relay-springs" 132 and 131, "line-conductor" 31, spring 22, contact-point 24, conductor 505, receiver 2, conductor 506, secondary winding 18 of the induction-coil 16, contact-point 27, spring 29 to springs 6 and 5, contact-point 23, spring 21, "vertical-line-conductor" 30, "line-switching-relay-springs" 128 and 129, conductor 437, "vertical-line-wiper" 112, "vertical-trunk-conductor" 438,

"line-switching-relay-springs" 228 and 229, conductor 460, "vertical-line-wiper" 210, "vertical-trunk-conductor" 461, "vertical-line-relay" 235, conductor-terminal 526 to winding 410 of induction-coil 408, back to conductor 527. The subscriber, hearing the busy signal, hangs up his receiver, restoring the switches to their normal condition, and attempts the call at some later time. In the 10 next instance, as suggested, the subscriber #2241 may be busy by reason of having called some other subscriber. His shaft 370 of the "first-selector" F (Fig. 2) being raised, and stop-arm 379 being out of the 15 way, the spring 381 is in contact with the ground-spring 380. The result of this is, that a guarding potential is established at the "private-contact" of the "connector-bank" which corresponds to #2241. This 20 was shown to be the first contact of the fourth row of the "connector-bank" 311 (Fig. 5), as well as other points in multiple.

This guarding potential is established from ground G at battery B to ground G¹⁰ 25 at the "first-selector" F (Fig. 2), through contact-point 380, spring 381, over "private-normal-conductor" 517 to the "private-contact-point" of the "connector-bank." It is evident that these conditions are similar to 30 the ones existing in the last instance. Now, should the subscriber at station A, after the shaft of "connector" E is raised so that the wipers are engaged with the first contact of the fourth row of their respective banks, 35 press his button 20, the "side-switch" being in the second position, the "connector" would be released as before. On pressing his signaling-button 26 he would receive the busy signal in a manner and through a circuit already explained.

With the exception of the "side-switch," and of the provision of other improvements, as hereinbefore described, the said "selectors" are of the general type shown and described in Patent No. 815,321, granted 45 March 13, 1906, to Keith, Erickson & Erickson. Similarly, the herein described "connectors" are, it will be seen, of the general type shown and described in Patent No. 815,176, granted March 13, 1906, to Keith, 50 Erickson & Erickson.

With my improved construction and arrangement, it is obvious that the system has many substantial advantages over the old 55 arrangements. For example, the "selectors" have no "side-switches," whereby a feature is omitted which is more or less undesirable, owing to the large number of parts that must work together and that require very delicate adjustment which is difficult to maintain. Owing to the comparatively 60 large amount of work which the "selectors" are called upon to perform, and owing to the consequent greater amount of wear and tear to which the "side-switches" of these

other "selectors" have been subjected, as compared with the mechanism of the "connectors," these particular switching devices known as "side-switches" have given greater trouble in "selectors" than they have in "connectors." It will also be seen that, notwithstanding the elimination of the said "side-switches" from the "selectors," all bridging coils in the "selectors" are cut off or removed from the talking-circuit between 70 a calling and a called subscriber. In fact, only two bridges remain across the talking-circuit, and these two are both found in the "connector" employed between any calling subscriber and any called subscriber. In 75 80 one of these bridges there are included the "line-relays" which are located at the calling subscriber's side of the condensers in the "connector." As explained, these "line-relays" are used by the calling subscriber for 85 initiating the release of all switches which he may have put in use in establishing connection with another subscriber's line. The second bridge consists of the "back-release-relays" at the called subscriber's side of the 90 condensers in the "connector." These "back-release-relays" are used by the called subscriber for releasing the "connector," as, for example, when the calling subscriber has failed to restore his receiver and thereby 95 effect a release of all the switches between the two subscribers' lines. Again, the improved construction and circuit arrangement permits the use of the "release-magnet" of 100 a "connector" in series with the "release-relay" of a "second-selector," for example, and in a similar manner the use of the "release-magnet" of a "second-selector" in series with the "release-relay" of a "first-selector"; and in this way, the "release-relay" of 105 the switch in each preceding group is connected in series with the "release-magnet" in the switch in the immediately succeeding group—that is, the "back-release-relay" of 110 a "first-selector" in an established connection is, for example, connected in series with the "release-magnet" of the "second-selector" with which it is connected. With this arrangement, the "release-magnets" are employed for insuring a positive guarding potential at the "private-bank-contacts" corresponding to the line connections in use, so as to make it impossible for a third subscriber to cut-in and make connection with any one of such line connections, even though 115 the effort by the third subscriber to get connection with one of the busy line connections should be made at the very instant that the "release-circuit," including a "release-relay" and a "release-magnet," and also including 120 a multiple of the "private-bank-contact" corresponding to the multiple "line-contacts" with which the third subscriber attempts to get connection, is closed by the calling subscriber; for example, after the conversation 125 130

over the established talking-circuit has terminated. For this reason, the "release-relays" are preferably of $\frac{1}{2}$ ohm resistance, while the "release-magnets" are each preferably of about 60 ohms resistance; and in this connection it may also be stated that the "private-magnets" are preferably of 350 ohms resistance. Thus, as explained, the resistance from the grounded pole of the battery to the "private-bank-contacts" is always less than the resistance from the non-grounded pole of the battery through the "release-magnets" to the said contacts, so that current from the positive pole of the battery will always flow from a busy "private-bank-contact" through the necessary coils of any other switching machine which a third subscriber may operate and thus attempt to cut-in on the established circuit, even should such attempt be made at the very instant that the switches are being released between the calling and called subscribers. These "release-relays" are preferably so adjusted that they will always pull up or energize when included in a circuit of 80 ohms resistance or less, but cannot pull up or energize when included in a circuit of 90 ohms resistance. Consequently, the 350 ohms resistance in the "private-magnets" gives a wide margin with respect to various possibilities and contingencies—that is, with respect to certain situations by which a "private-magnet" may at times be placed in series with a "release-relay." Furthermore, it is not only possible, under certain conditions, for a "private-magnet" to be placed momentarily in series with the "release-relay," but it is also possible for a "private-magnet" with more or less resistance in parallel therewith to be placed in series with a "release-relay." As explained, however, the "release-relays" will not pull up or energize when included in a circuit of 90 ohms or more, and for this reason the resistance in the "private-magnet" temporarily connected in series with a "release-relay" may be cut down or reduced considerably without jeopardizing the desired functions and operations of the different parts. With my improved arrangement, the "release-magnets" perform their usual functions of releasing the switching machines, and in addition serve as suitable resistance for insuring against neutralization of the positive or guarding potential which is necessarily and preferably maintained at all the busy "private-bank-contacts" until the line connections and line-terminals corresponding to these "private-bank-contacts" are, together with the switches or switching machines by which they were put in use, completely restored to their normal or non-busy conditions.

From the foregoing it will be seen that my improved construction and circuit arrange-

ment presents, among others, the following aspects and advantages, namely: that the "first-selectors" are each provided with a relay known as a "line-switching-relay", and adapted to operate in a manner similar to the so-called bridge-cut-off-relay in the "first-selector-switches" of the aforesaid general type, these "line-switching-relays" becoming energized as soon as a calling "connector" seizes a subscriber's line and places the "private-normal-conductor" in connection with the grounded terminal of the battery, and the energizing of the "line-switching-relay" at this time being for the purpose of removing a certain bridge from across the called line, although other duties or functions of these "line-switching-relays" are involved in the general operation of the system, as previously explained; that upon the first vertical step of the shaft of a "first-selector", a guarding potential is established at the "private-bank-contacts" of the "connector-banks" that correspond to the number of the line of the "first-selector" that is being operated, this guarding potential being established from a ground-point that is brought into use only after the switch-shaft is off normal, so to speak—that is, moved from its position of rest—and it being observed that this guarding potential reaches the said "private-bank-contact" or contacts from the positive pole of the battery over the "private-normal-conductor"; that when the "private-normal-conductor" is grounded, by the raising of the switch-shaft, the "line-switching-relay" thereof is prevented from being energized before said shaft is rotated, by the provision of a cam and a number of so called cam-springs, it being understood that it is not desirable that this "line-switching-relay" be energized at this juncture, as such energizing would interfere with the call; that as soon as the shaft of the "first-selector" starts to rotate, and after the wipers thereof encounter a series of busy trunk-line-terminals, the "line-switching-relay" is desirably prevented from becoming energized during its rotation by the provision and construction of certain switch-springs known as "private-springs", as they are operated by the so-called "private-magnet", and which are adapted to short-circuit said "line-switching-relay"; that by a special arrangement of the shaft-cam, the cam-springs and "private-springs", as hereinbefore described, any "first-selector" may be released, if such is desirable, even at a time while the shaft of such "first-selector" is rotating; that by the arrangement and use of certain of the aforesaid "private-springs", as fully set forth, the shaft of any "selector" is enabled to rotate its wipers past the terminals of all busy trunk-lines; that by the use of certain springs directly under the control of the so-called

"line-relays", a "first-selector", before it gives up the control of its releasing mechanism to another switch, may be released directly by the said "line-relays"; that by the 5 use of certain of the said "private-springs", a "first-selector", after it has picked out or selected an idle or non-busy trunk-line, then establishes a guarding potential at all "private-bank-contacts" corresponding to such 10 selected trunk-line; that through the medium of the aforesaid cam-springs, and through the medium of the said so-called "back-release-relay", a "first-selector" places its release mechanism directly under the control 15 of a switch in the next succeeding group; that by means of the combined arrangement and cooperation of the "line-switching-relay", the "private-magnet" and the "release-relay", together with the switch-springs under 20 the control of these relays, any "first-selector" may be released at any stage of its calling operation, or even after the call has been completed, the same being true, of course, of any "second-selector"; that in all 25 "second-selectors" the so-called "line-relays" are normally off the line—that is, normally disconnected from the line—but as soon as a "first-selector" trunks to or makes connection with one of said "second-selectors", the 30 "line-switching-relay" of such "second-selector" is then energized, and these normally-disconnected "line-relays" are then brought into operative relation to the line; that as soon as a "second-selector-shaft" 35 begins to rotate, and if the wipers thereof encounter a series of terminals connected with busy trunk-lines, the "line-switching-relay" of the "selector" is maintained in an energized condition during such rotation, 40 and this energizing being possible by reason of the arrangement of the "private-springs" under the control of the "second-selector-private-magnet"; that by the arrangement and use of some of the aforesaid "private-springs" in connection with a cam and a 45 number of cam-springs, as explained, a "second-selector" may be released even while its shaft is rotating; that some of said "private-springs" enable the "second-selector-wipers" 50 to be rotated past the terminal of a busy trunk-line, as explained, while, by the use of certain springs as stated, a guarding potential for protecting a selected trunk-line is also established by way of the "second-selector-release-relay"; that after a "first-selector" is connected with a "second-selector", the latter may, at any time before it 55 breaks the connection with the line, and by its "line-relays", effectively energize its own "release-magnet", and also energize the "release-relay" of the said "first-selector", this being accomplished through the medium 60 of two springs, as previously explained, which are directly under the control of said 65 "line-relay" in the "second-selector", it be-

ing observed that during the making of a call, and after a "first-selector" has truned to or connected with a "second-selector", the said "second-selector" may, before it trunks to or connects with a "connector", then be released by its own "line-relays", and may at the same time release the said "first-selector"; that through the medium of the shaft-cam, the cam-springs operated thereby, and certain "private-springs", as explained, the "line-relays" of a "second-selector" are desirably switched out of connection with the line, while the release mechanism of such "second-selector" is then surrendered to the control of the switch in the next group—that is, after it has selected an idle or non-busy trunk-line; that the "back-release" of the first and second "selectors" is made possible by a suitable arrangement of certain of the "private-springs", as explained, in connection with the "release-relays" of these switches and the springs controlled thereby; and that the "connector" is of any suitable, known or approved general type, but is, as a feature of special improvement, provided with a "release-magnet" adapted, during the use of the "connector" between subscribers' lines, to remain in series with the "release-relay" of the switch in the previous group, the "release-circuit" thus extending between switches, and including a "release-magnet" and a "release-relay" in series, being left open, of course, until such time as either subscriber may desire to effect its closure for the purpose of energizing the said magnet and relay, and for the purpose of thereby releasing or restoring the switching machines to which the said magnet and relay are allotted.

The resistances of the various coils, including those for which no particular resistance has been specified, can be varied or adjusted to suit the requirements of different situations. It will be understood, of course, that the instruments and devices employed at the subscribers' stations may be of any suitable, known or approved character, consistent with the functions and general mode of operation herein described.

Inasmuch as the relays 125 and 225 are each at times connected in series with a "rotary-magnet", such as the magnet 58 of the "first-selector", or the magnet 158 of the "second-selector", and inasmuch as at such times it is important that the "rotary-magnet" be not energized, the said relays 125 and 225 are each preferably of 2000 ohms resistance, more or less, thereby precluding all possibility of the energizing of a "rotary-magnet" when temporarily connected in series with one of the so-called "line-switching-relays".

It will be understood that the "vertical" and "rotary" "line-normals" 30^a and 31^a extend to the "line-bank-contacts" of a suit-

able number of conductors—that is, the multiple-line-contacts or terminals which are included in the banks of a suitable number of “connectors”, and which correspond to 5 the line of the calling subscriber. Also, it will be readily understood that the calling subscriber's “private-normal” 108^a extends to the corresponding “private-bank-contacts” in the said other “connectors”, whereby a 10 guarding potential is always established at the private-bank-contacts corresponding to the calling subscriber's line, both when the said subscriber calls out, and when some other subscriber uses one of 15 said “connectors” for calling or making connection with the line of said calling subscriber at station A. Referring to Fig. 1, it will also be seen that the “line-contacts” 115 of the “first-selector” are multiplied 20 with the corresponding “line-contacts” 115^a of another “first-selector”, and so on to the corresponding “line-contacts” of any suitable number of “first-selectors”, whereby any of these “first-selectors” may be used 25 for getting connection with the trunk-line consisting of the conductors 438 and 439. With this arrangement, the “private-bank-contact” 111 is, of course, multiplied with all corresponding “private-bank-contacts” in all 30 “selectors” having multiples of the “line-contacts” 115. For example, as shown, the contact 111 is multiplied with the corresponding “private-bank-contact” 111^a in the “first-selector” having the “line-contacts” 115^a. For similar reasons, the “line-contacts” 213 of the “second-selector” are multiplied with the “line-contacts” 213^a of another “second-selector”, while the “private-bank-contact” 209 is multiplied with the corresponding “private-bank-contact” 209^a of 35 the “second-selector” having the contacts 213^a; and these “line” and “private” bank-contacts are multiplied with corresponding contacts in any suitable number of “second-selectors”, whereby any one of these “second-selectors” can be employed for making 40 connection with the trunk-line consisting of the conductors 461 and 462. Referring to Fig. 2, the “line-contacts” 315 of the “connector” are multiplied with the “line-contacts” 315^a of another “connector”, and also with the corresponding multiple-line-contacts of all other “connectors” provided 45 for the purpose of establishing connection with the subscriber's line running to station S. In order that the desired guarding potential may be established, whenever this subscriber's line is busy or in use in any way, the “private-bank-contact” 311 is multiplied 50 with the “private-bank-contact” 311^a of the “connector” having the contacts 315^a; and also with all other “private-bank-contacts” in other “connectors” having multiples of 55 these particular “line-contacts” or “line-terminals”. It will be readily understood, 60

however, that the number and character of the switches necessary for connecting up any two subscribers' lines will depend upon the size and character of the system as a whole, and that the “selectors” and “connectors” of the system may be divided into groups and installed in any suitable, known or approved manner. 70

Throughout the foregoing description of my improved automatic telephone apparatus, 75 and in the following claim, the term “selector” will be understood to mean any switching machine which is capable of automatically selecting and making connection with an idle trunk-line—that is to say, which is capable of being controlled directly by the subscriber for the purpose of selecting a certain group of trunk-lines, but which then escapes from the control of the subscriber and proceeds automatically to select out of 80 said group a trunk-line which is not busy. As described and shown, the specific expedient for accomplishing this result consists in automatically maintaining the rotation of 85 the switch-shaft until the wipers thereon make contact with terminals corresponding to an idle trunk-line. Also, it will be understood that the term “connector”, in the said description and claims, means any switching machine which can be employed for 90 not only picking out and selecting a certain group of lines, such as subscribers' lines, but which can then also be employed for picking out and making connection with any particular line or member of such group, and which will not of its own accord make 95 connection or attempt to make connection with some other line if the particular or desired line is busy, but which, on the contrary, will establish no connection whatever if the particular or desired line is in use, as, for example, by automatically restoring itself to its normal condition as soon as it finds that the desired or particular line is busy. This I believe is the accepted 100 definition of the term “selector,” and is also the accepted definition of the term “connector”, both words now having a definite and well defined meaning in the terminology relating to automatic telephone 105 apparatus. 110

What I claim as my invention is:—

1. An automatic telephone system comprising a calling subscriber's line and a called subscriber's line connected through the medium of means including a plurality of electrically-propelled and step-by-step switching machines, one of said machines having a “release-magnet” and suitable mechanism whereby said magnet is operative to effect a restoration of the machine to its normal condition, another of said machines having a similar “release-magnet” controlled by a “release-relay”, and the first-mentioned “release-magnet” having an en- 120
- 125
- 130

- ergizing circuit which is open during conversation between the subscribers, and which includes a winding of said relay, the resistance of the said "release-magnet" thus included in series with the "release-relay" being greater than that of the latter.
2. An automatic telephone system comprising a calling subscriber's line and a called subscriber's line connected together through the medium of means including a trunk-line and electrically-propelled and step-by-step actuated switching apparatus, said apparatus including a "release-magnet" and a "release-relay", and a normally open "release-circuit" including a conductor of said trunk-line and the windings of both the magnet and the relay.
3. An automatic telephone system comprising a calling subscriber's line and a called subscriber's line connected together for conversational purposes through the medium of means including electrically-propelled and step-by-step-actuated switching apparatus, a pair of trunk-line-conductors, a third trunk-line-conductor, and a "release-circuit" for said apparatus including said third trunk-line-conductor, said circuit including also a plurality of the electro-magnets of the switching apparatus, each magnet being provided with an armature.
4. An automatic telephone system comprising an established talking-circuit, a battery, a set of multiple-contacts connected with the positive pole of the battery while the subscribers are conversing, a "release-relay", a "release-magnet", a pair of trunk-line-conductors, a third trunk-line-conductor, and a normally-open "release-circuit" including said relay and magnet and battery, and also including the said third trunk-line-conductor and one of said contacts, said "release-magnet" being located in the "release-circuit" at a point between the negative pole of the battery and the multiple-contact included in such circuit, the said relay being disposed in the "release-circuit" at a point between the positive pole of the battery and the said contact in the circuit, and the said magnet being of higher resistance than the said "release-relay", whereby a positive potential is maintained at all of said multiple-contacts while the "release-circuit" is open, and also at the instant that the "release-circuit" is closed.
5. An automatic telephone system comprising a calling subscriber's line and a called subscriber's line, a plurality of "selectors" and a "connector" temporarily maintained in operative condition between said lines, the "first-selector" being provided with a "release-relay", the "second-selector" having a "release-magnet", and there being a temporarily established normally-open "release-circuit" extending between the first and second "selectors", said "release-circuit" including said relay and magnet, and the magnet being of higher resistance than the relay, whereby the resistance in the said "release-circuit" is greater at one side of any point between the relay and magnet than at the other side thereof.
6. An automatic telephone system comprising a plurality of "selectors" temporarily retained in condition to maintain a trunk-line connection, one of said "selectors" having a "release-relay", another "selector" having a "release-magnet", and there being a temporarily established normally open "release-circuit" including said relay and magnet, said "release-circuit" being closed during conversation at all points except a single point between the relay and magnet, and there being means under the control of a calling subscriber for effecting a closure of said open point in the "release-circuit".
7. An automatic telephone system comprising a "first-selector" provided with a "release-relay", a "second-selector" provided with a "release-magnet", a battery, a set of multiple-contacts, and a temporarily closed or charged circuit including said relay and magnet and battery, and also including one of said contacts, the said relay and magnet being disposed in said circuit at opposite sides of the contact included therein, and the said magnet being of higher resistance than the relay, whereby any connection temporarily established with one of said multiple-contacts will receive current from the positive pole of the battery through the said "release-relay".
8. In an automatic telephone exchange system, the combination of a calling subscriber's line and a called subscriber's line connected through the medium of means including a plurality of electrically-propelled and step-by-step switching machines, one of said machines having a "release-magnet" and suitable mechanism whereby said magnet is operative to effect a restoration of the machine to its normal condition, another of said machines having a similar "release-magnet" controlled by a "release-relay", and the first-mentioned "release-magnet" having an energizing circuit which is open during conversation between the subscribers, and which includes a winding of said relay, the resistance of the said "release-magnet" thus included in series with the "release-relay" being greater than that of the latter, said switching machinery including also a rotatable and endwise-movable switch-shaft provided with a pair of "line-wipers", and also with a third or so-called "private-wiper" which is always temporarily connected with the ground as soon as the said shaft is put in operation, said "private-wiper" being included in the "release-circuit".
9. In an automatic telephone exchange

- system, the combination of a calling subscriber's line and a called subscriber's line connected together through the medium of means including electrically-propelled and step-by-step-actuated switching apparatus, said apparatus including a "release-magnet" and a "release-relay", and a normally open "release-circuit" including the windings of both the magnet and the relay, said switching apparatus including also a rotatable and endwise-movable switch-shaft provided with a pair of "line-wipers", and also with a third or so-called "private-wiper" which is always temporarily connected with the ground as soon as the said shaft is put in operation, said "private-wiper" being included in the "release-circuit".
10. In an automatic telephone exchange system, the combination of a calling subscriber's line and a called subscriber's line connected together for conversational purposes through the medium of means including electrically-propelled and step-by-step-actuated switching apparatus, a pair of trunk-line conductors, a third trunk-line-conductor, and a "release-circuit" for said apparatus including said third trunk-line-conductor, and including also a plurality of the electro-magnets of the switching apparatus, each magnet being provided with an armature, said switching apparatus including also a rotatable and endwise-movable switch-shaft provided with a pair of "line-wipers", and also with a third or so-called "private-wiper" which is always temporarily connected with the ground as soon as the said shaft is put in operation, said "private-wiper" being included in the "release-circuit".
20. 11. In an automatic telephone exchange system, the combination of an established talking-circuit, a battery, a set of multiple-contacts connected with the positive pole of the battery while the subscribers are conversing, a "release-relay", a "release-magnet", a pair of trunk-line conductors, a third trunk-line-conductor, and a normally open "release-circuit" including said relay and magnet and battery, and also including the said third trunk-line-conductor and one of said contacts, said "release-magnet" being located in the "release-circuit" at a point between the negative pole of the battery and the multiple-contact included in such circuit, the said relay being disposed in the "release-circuit" at a point between the positive pole of the battery and the said contact in the circuit, and the said magnet being of higher resistance than the said "release-relay", whereby a positive potential is maintained at all of said multiple-contacts while the "release-circuit" is open, and also at the instant that the "release-circuit" is closed, there being in the system a rotatable and endwise-movable switch-shaft provided with a pair of "line-wipers", and also with a third or so-called "private-wiper" which is always temporarily connected with the grounded pole of the battery as soon as the said shaft is put in operation, said "private-wiper" being included in the "release-circuit".
30. 12. In an automatic telephone exchange system, the combination of a calling subscriber's line and a called subscriber's line, a plurality of "selectors" and a "connector" temporarily maintained in operative condition between said lines, the "first-selector" being provided with a "release-relay", the "second-selector" having a "release-magnet", and there being a temporarily established normally open "release-circuit" extending between the first and second "selectors", said "release-circuit" including said relay and magnet, and the magnet being of higher resistance than the relay, whereby the resistance in the said "release-circuit" is greater at one side of any point between the relay and magnet than at the other side thereof, said system including also a rotatable and endwise-movable switch-shaft embodied in one of the "selectors" and provided with a pair of "line-wipers", and also with a third or so-called "private-wiper" which is always temporarily connected with the ground as soon as the said shaft is put in operation, said "private-wiper" being included in the "release-circuit".
40. 13. In an automatic telephone exchange system, the combination of a plurality of "selectors" temporarily retained in condition to maintain a trunk-line connection, one of said "selectors" having a "release-relay," another "selector" having a "release-magnet," and there being a temporarily established normally open "release-circuit" including said relay and magnet, said "release-circuit" being closed during conversation at all points except a single point between the relay and magnet, and there being means under the control of a calling subscriber for effecting a closure of said open point in the "release-circuit," said system including also a rotatable and endwise-movable switch-shaft constituting a part of one of the "selectors" and provided with a pair of "line-wipers," and also with a third or so-called "private-wiper" which is always temporarily connected with the ground as soon as the said shaft is put in operation, said "private-wiper" being included in the "release-circuit."
50. 14. In an automatic telephone exchange system, the combination of a "first-selector" provided with a "release-relay," a "second-selector" provided with a "release-magnet," a battery, a set of multiple-contacts, and a temporarily closed or charged circuit including said relay and magnet and battery, and also including one of said contacts, the said relay and magnet being disposed in said circuit.

cuit at opposite sides of the contact included therein, and the said magnet being of higher resistance than the relay, whereby any connection temporarily established with one of said multip e-contacts will receive current from the positive pole of the battery through the said "release-relay," said system including also a rotatable and endwise-movable switch-shaft constituting a part of one of the "selectors" and provided with a pair of "line-wipers," and also with a third or so-called "private-wiper" which is always temporarily connected with the grounded pole of the battery as soon as the said shaft is put in operation, said "private-wiper" being included in the "release-circuit."

15. An automatic telephone system comprising two subscribers' lines temporarily connected for conversational purposes, said connection being established through the medium of a "connector" and one or more "selectors," a suitable battery or other source of electric current supply, and a temporarily established and normally open "release-circuit" extending between the "connector" and a "selector" and maintained in condition to be closed by either subscriber through the medium of suitable means, said "connector" being provided with a "release-magnet" included in said circuit, and the "selector" having a "release-relay" also included in said "release-circuit", said battery being included in the "release-circuit" at a point between the windings of said magnet and relay, and there being a plurality of "private-bank-contacts" which are multiplied together and connected with the said "release-circuit" at a point between the said magnet and relay, the magnet being of higher resistance than the relay, whereby the guarding potential established at the said multiple-contacts is of the desired polarity, said system including also a rotatable and endwise-movable switch-shaft constituting part of a "selector" and provided with a pair of "line-wipers", and also with a third or so-called "private-wiper" which is always temporarily connected with the grounded pole of the battery as soon as the said shaft is put in operation, said "private-wiper" being included in the "release-circuit".

16. An automatic telephone system comprising subscribers' lines temporarily connected together through the medium of a "connector" and one or more "selectors," said "connector" having a releasing mechanism, and the "selector" with which the "connector" is connected having a release mechanism controlled by a "release-relay," and there being three trunk-line-conductors extending between the said "connector" and "selector", together with a battery included in a normally open "release-circuit" which includes the windings of said magnet and relay, and which also includes the third trunk-line-conductor, whereby the closing of the temporarily established "release-circuit," by either subscriber, brings about a simultaneous energizing of both the magnet and the relay, and a consequent releasing of the "connector" and "selector".

17. In an automatic telephone exchange system, the combination of two subscribers'

lines temporarily connected for conversational purposes, said connection being established through the medium of a "connector" and one or more "selectors", a suitable battery or other source of electric current supply, and a temporarily established and normally open "release-circuit" extending between the "connector" and a "selector" and maintained in condition to be closed by either subscriber through the medium of suitable means, said "connector" being provided with a "release-magnet" included in said circuit, and the "selector" having a "release-relay" also included in said "release-circuit", said battery being included in the "release-circuit" at a point between the windings of said magnet and relay, and there being a plurality of "private-bank-contacts" which are multiplied together and connected with the said "release-circuit" at a point between the said magnet and relay, the magnet being of higher resistance than the relay, whereby the guarding potential established at the said multiple-contacts is of the desired polarity, said system including also a rotatable and endwise-movable switch-shaft constituting part of a "selector" and provided with a pair of "line-wipers", and also with a third or so-called "private-wiper" which is always temporarily connected with the grounded pole of the battery as soon as the said shaft is put in operation, said "private-wiper" being included in the "release-circuit".

18. In an automatic telephone exchange system, the combination of subscribers' lines temporarily connected together through the medium of a "connector" and one or more "selectors", said "connector" having a releasing mechanism, and the "selector" with which the "connector" is connected having a release mechanism controlled by a "release-relay", and there being three trunk-line-conductors extending between the said "connector" and "selector", together with a battery included in a normally open "release-circuit" which includes the windings of said magnet and relay, and which also includes the third trunk-line-conductor, whereby the closing of the temporarily established "release-circuit", by either subscriber, brings about a simultaneous energizing of both the magnet and the relay, and a consequent releasing of the "connector" and "selector", said system including also a rotatable and endwise-movable switch-shaft constituting part of a "selector" and provided with a pair of "line-wipers", and also with a third or so-called "private-wiper" which is always temporarily connected with the grounded pole of the battery as soon as the said shaft is put in operation, said "private-wiper" being included in the "release-circuit".

19. An automatic telephone system com-

- prising an electrically-propelled and step-by-step-actuated switching machine provided with a "release-relay", another switching machine provided with a "release-magnet" and a so-called "private-magnet", a suitable battery, and a normally open "release-circuit" including said battery and relay and "release-magnet" in series, together with so-called "private-switch-contacts" also included in said "release-circuit" at a point between the relay and "release-magnet", said "release-magnet" being of higher resistance than the relay, and the said "private-magnet" being of higher resistance than the "release-magnet", whereby the "release-relay" may be energized while connected in series with the "release-magnet", but whereby said "release-relay" will never become energized operatively while connected in series with any "private-magnet" in the exchange similar to the said "private-magnet".

20. An automatic telephone system comprising a plurality of switching machines, each having a "release-relay" and a "release-magnet" and a so-called "private-magnet", together with a suitable battery and suitable circuit connections for producing the desired results, the "release-magnets" being of higher resistance than the "release-relays", but any "release-relay" being adapted to be energized when connected in series with any "release-magnet", and the said "private-magnets" being each of such high resistance that any "release-relay" cannot become energized operatively when temporarily or momentarily connected in series with a "private-magnet".

21. An automatic telephone system comprising a plurality of switching machines, each having a "release-relay" and a "release-magnet" and a so-called "private-magnet", together with a suitable battery and suitable circuit connections for producing the desired results, the "release-magnets" being of higher resistance than the "release-relays", but any "release-relay" being adapted to be energized when connected in series with any "release-magnet", and the said "private-magnets" being each of such high resistance that any "release-relay" cannot become energized operatively when temporarily or momentarily connected in series with a "private-magnet", the resistance of the "private-magnets" being also of such character that any "release-relay" will not energize operatively when temporarily connected in series with a plurality of the said "private-magnets" connected in parallel.

22. An automatic telephone system comprising a calling subscriber's line and a called subscriber's line temporarily connected together for conversational purposes, switching machinery involving a "release-relay" and a "release-magnet", together with a battery included in a "release-circuit" in which the said relay and magnet are connected in series, said "release-circuit" having a switch-point which is open during conversation, and means including a pair of "line-relays" whereby one of said subscribers may close the said switch-point after the conversation is terminated, and thereby effect a release and restoration of the switching machinery.

23. An automatic telephone system comprising a plurality of electrically-propelled and step-by-step-actuated switching machines each provided with release mechanism operated by a "release-magnet", and each having a "release-relay" for controlling the energizing of its "release-magnet", any switching machine employed in establishing connection between two subscribers always having its "release-relay" temporarily connected in series with the "release-magnet" of any succeeding machine employed for the same purpose, a battery for furnishing all necessary current, and suitable means whereby either a calling or a called subscriber may effect a closure of the circuit including a "release-relay" and a "release-magnet", and thereby effect a release or restoration of the switching machines by which the connection was established between the two subscribers' lines.

24. An automatic telephone system comprising a couple of electrically-propelled and step-by-step-actuated switching machines temporarily retained in condition to maintain an established talking-circuit, each machine having an electro-magnet provided with an armature having suitable or desired functions, a temporarily established normally open "release-circuit" including the windings of both of said electro-magnets, a battery included in said "release-circuit", and means under the control of a subscriber for effecting a closure of said "release-circuit", after the conversation is terminated, for the purpose of energizing both of said electro-magnets and thereby bringing about a release or restoration of both of said switching machines.

25. An automatic telephone system comprising a calling subscriber's line and a called subscriber's line temporarily connected together for conversational purposes through the medium of a plurality of "selectors" and a "connector", means for supplying current for operating the said "selectors" and "connector", the "first-selector" having a pair of "line-relays" which are normally bridged across the calling subscriber's line, but which are temporarily cut off from the line while the talking-circuit is established between the two subscribers, and the "second-selector" having a pair of "line-relays" which are normally disconnected

from the "line-circuit", and which are also disconnected therefrom during the use of the said circuit for talking purposes and there being suitable provisions for connecting and disconnecting the line-relays.

26. An automatic telephone system comprising an electrically-propelled and step-by-step-actuated switching machine of that character known as a "selector", and means 10 for supplying current for operating said machine, the said switching machine being provided with a pair of "line-relays" which are always disconnected from the "line-circuit" while the machine is in its normal or 15 at rest condition, or while the machine is in use for maintaining the continuity of an established talking-circuit, but which are connected with the "line-circuit" while the said switching machine is being operated or in 20 motion and there being suitable provisions for connecting and disconnecting the line-relays.

27. An automatic telephone system comprising a trunk-line, a step-by-step switching mechanism for including said trunk-line in any one of a number of possible "line-circuits", and a pair of "line-relays" for controlling the step-by-step operation of said mechanism, the said relays being normally 30 disconnected from the said trunk-line, but being bridged across the trunk-line while the said mechanism is in motion, together with a battery having one pole grounded and the other pole permanently connected to the 35 said bridge at a point between said relays and there being suitable provisions for connecting and disconnecting the line-relays.

28. In an automatic telephone exchange system, the combination of an electrically-propelled and step-by-step-actuated switching machine provided with a "release-relay", another switching machine provided with a "release-magnet" and a so-called "private-magnet", a suitable battery, and a normally 40 open "release-circuit" including said battery and relay and "release-magnet" in series, together with so-called "private-switch-contacts" also included in said "release-circuit" 45 at a point between the relay and "release-magnet", said "release-magnet" being of higher resistance than the relay, and the said "private-magnet" being of higher resistance than the "release-magnet", whereby the "release-relay" may be energized while connected in series with the "release-magnet", but whereby said "release-relay" will never become energized operatively while connected in series with any "private-magnet" 50 in the exchange similar to the said "private-magnet", the switching machinery including also a rotatable and endwise-movable switch-shaft provided with a pair of "line-wipers", and also with a third or so-called "private-wiper" which is always temporarily connected with the grounded pole of the battery 55

as soon as the said shaft is put in operation, said "private-wiper" being included in the "release-circuit".

29. In an automatic telephone exchange system, the combination of a plurality of switching machines, each having a "release-relay" and a "release-magnet" and a so-called "private-magnet", together with a suitable battery and suitable circuit connections for producing the desired results, the "release-magnets" being of higher resistance than the "release-relays", but any "release-relay" being adapted to be energized when connected in series with any "release-magnet", and the said "private-magnets" being each of such high resistance that any "release-relay" cannot become energized operatively when temporarily or momentarily connected in series with a "private-magnet", the switching machinery including also a rotatable and endwise-movable switch-shaft provided with a pair of "line-wipers", and also with a third or so-called "private-wiper" which is always temporarily connected with the grounded pole of the battery as soon as the said shaft is put in operation, said "private-wiper" being included in the "release-circuit".

30. In an automatic telephone exchange system, the combination of a plurality of switching machines, each having a "release-relay" and a "release-magnet" and a so-called "private-magnet", together with a suitable battery and suitable circuit connections for producing the desired results, the "release-magnets" being of higher resistance than the "release-relays", but any "release-relay" being adapted to be energized when connected in series with any "release-magnet", and the said "private-magnets" being each of such high resistance that any "release-relay" cannot become energized operatively when temporarily or momentarily connected in series with a "private-magnet", the resistance of the "private-magnets" being also of such character that any "release-relay" will not energize operatively when temporarily connected in series with a plurality of the said "private-magnets" connected in parallel, the switching machinery including also a rotatable and endwise-movable switch-shaft provided with a pair of "line-wipers", and also with a third or so-called "private-wiper" which is always temporarily connected with the grounded pole of the battery as soon as the said shaft is put in operation, said "private-wiper" being included in the "release-circuit".

31. In an automatic telephone exchange system, the combination of a calling subscriber's line and a called subscriber's line temporarily connected together for conversational purposes, switching machinery involving a "release-relay" and a "release-magnet", together with a battery included in

- a "release-circuit" in which the said relay and magnet are connected in series, said "release-circuit" having a switch-point which is open during conversation, and means including 5 a pair of "line-relays" whereby one of said subscribers may close the said switch-point after the conversation is terminated, and thereby effect a release and restoration of the switching machinery, the switching machinery including also a rotatable and endwise-movable switch-shaft provided with a pair of "line-wipers", and also with a third or so-called "private-wiper" which is always temporarily connected with the grounded 70 pole of the battery as soon as the said shaft is put in operation, said "private-wiper" being included in the said "release-circuit".
- 10 32. In an automatic telephone exchange system, the combination of a plurality of electrically-propelled and step-by-step actuated switching machines each provided with release mechanism operated by a "release-magnet", and each having a "release-relay" for controlling the energizing of its "release-magnet", any switching machine employed in establishing connection between two subscribers always having its "release-relay" temporarily connected in series with the "release-magnet" of any succeeding machine employed for the same purpose, a battery for furnishing all necessary current, and suitable means whereby either a calling or a called subscriber may effect a closure 20 of the circuit including a "release-relay" and a "release-magnet", and thereby effect a release or restoration of the switching machines by which the connection was established between the two subscribers' lines, the switching machinery including also a rotatable and endwise-movable switch-shaft provided with a pair of "line-wipers", and also with a third or so-called "private-wiper" which is always temporarily connected with the grounded pole of the battery as soon 30 as the said shaft is put in operation, said "private-wiper" being included in the "release-circuit."
- 15 33. In an automatic telephone exchange system, the combination of a couple of electrically-propelled and step-by-step-actuated switching machines temporarily retained in condition to maintain an established talking-circuit, each machine having an electro-magnet provided with an armature having suitable or desired functions, a temporarily established normally open "release-circuit" including the windings of both of said electro-magnets, a battery included in said "release-circuit", and means under the control of a subscriber for effecting a closure of said "release-circuit", after the conversation is terminated, for the purpose of energizing both of said electro-magnets and thereby bringing about a release or restoration 40 of both of said switching machines, the switching machinery including also a rotatable and endwise-movable switch-shaft provided with a pair of "line-wipers", and also with a third or so-called "private-wiper" which is always temporarily connected with the grounded pole of the battery as soon as the said shaft is put in operation, said "private-wiper" being included in the "release-circuit".
- 20 34. An automatic telephone system comprising a "selector" provided with a rotatable and endwise-movable switch-shaft, means including a plurality of electro-magnets for operating said shaft, a bank of "line-contacts", a pair of wipers on said shaft adapted to cooperate with said bank of contacts in establishing any one of a number of possible connections, a trunk-line with which said wipers are normally connected, means for supplying all necessary current, and a relay adapted as soon as energized to disconnect the said wipers from the trunk-line, and when de-energized to at once re-connect the wipers with the same trunk-line.
- 25 35. An automatic telephone system comprising a trunk-line, a bank of "line-terminals", switch-contacts adapted to cooperate with said terminals in making any one of a number of possible connections, electrically-propelled and step-by-step-actuated means for operating said switch-contacts, said contacts being normally connected with said trunk-line, means for supplying all necessary current, and a relay for controlling the normally closed connections between the said contacts and the trunk-line, adapted to hold the connection open as long as energized, and to close the same as soon as de-energized.
- 30 36. An automatic telephone system comprising a "selector" provided with switch-contacts for establishing any one of a number of possible connections, a trunk-line running to said "selector" and normally connected with certain of said contacts, a plurality of trunk-lines running from the "selector" and permanently connected with certain other contacts thereof, the "selector" having electrically-propelled and step-by-step-actuated mechanism for operating said contacts, and for thereby connecting said incoming trunk-line with any one of said outgoing trunk-lines, and a relay adapted as soon as energized to disconnect the said incoming trunk-line from said contacts with which it is normally connected, together with means for supplying all necessary current, there being also automatic means for maintaining the switch-contacts in operation until an idle outgoing trunk-line is found.
- 35 37. An automatic telephone system comprising first and second "selectors", the "second-selector" having an incoming main trunk-line leading from the "first-selector", a third trunk-line-conductor extending be-

tween the two "selectors", the "second-selector" having a pair of "line-wipers" normally connected with the said incoming trunk-line, and having a bank of "line-terminals" adapted to be engaged by said wipers and each connected with an outgoing trunk-line, means for supplying all necessary current, a relay for controlling the normally closed connection between the said 10 wipers and the incoming trunk-line, and an energizing circuit for said relay including the said third trunk-line-conductor.

38. An automatic telephone system comprising a main trunk-line, a pair of "line-relays" normally disconnected from said trunk-line, electrically-propelled and step-by-step-actuated switching apparatus adapted to be controlled by said relays, an additional trunk-line-conductor, an additional 15 relay for controlling the normally open connection between the said "line-relays" and the trunk-line, means for supplying all necessary current, and an energizing circuit for said additional relay including said 20 additional trunk-line-conductor.

39. An automatic telephone system comprising a rotatable and endwise-movable switch-shaft, electrically-propelled and step-by-step-actuated mechanism for operating 25 said shaft, normally open and normally closed switch-contacts both operated by the rotary movements of said shaft, and means for supplying all necessary current, together with a relay having a plurality of 30 energizing circuits controlled by said contacts.

40. An automatic telephone system comprising a rotatable and endwise-movable switch-shaft, wipers on said shaft, a bank of "line-terminals" adapted to be engaged by 40 said wipers when the shaft is operated, electrically-propelled and step-by-step-actuated mechanism for operating said shaft, normally open and normally closed switch-contacts adapted to be operated by the 45 rotary movements of said shaft, and means for supplying all necessary current, together with a relay having a plurality of energizing circuits controlled by said contacts.

50. An automatic telephone system comprising a "selector" having electrically-propelled and step-by-step-actuated switching apparatus, and having also a "release-magnet" and releasing mechanism whereby said 55 magnet only when energized and de-energized is operative to restore the "selector" to its normal condition, normally closed switch-contacts adapted to be separated or opened by the energizing of said "release-magnet", and closed together by the de-energizing of the same, and means for supplying all necessary current.

55. An automatic telephone system comprising a "selector" provided with a rotatable and endwise-movable switch-shaft,

wipers on said shaft, "line-terminals" adapted to be engaged by said wipers when the shaft is operated, electrically-propelled and step-by-step-actuated means for giving the shaft a step-by-step endwise movement, 70 similar means for giving the shaft a step-by-step rotary motion, said last-mentioned means having an energizing circuit provided with an automatic interrupter or circuit-breaker whereby the rotary motion of the shaft is automatically continued as long as the said circuit remains closed, and until an idle terminal is found by the said wipers, a relay for closing said circuit, and a circuit including a winding of said relay and 75 controlled by contacts thereof, said relay being adapted to close the said energizing circuit as soon as it is energized sufficiently to attract its armature, and to open the circuit as soon as de-energized, together with means for supplying all necessary current.

43. An automatic telephone system comprising a "first-selector," a "second-selector," and a battery for furnishing the current necessary for operating said "selectors," said "second-selector" having release mechanism operated by a "release-magnet," and a release-circuit in which the said battery and magnet are connected in series, said circuit having a plurality of 85 switch-points one of which is controlled by said "first-selector," the system also comprising a talking circuit independent of said release-circuit.

44. An automatic telephone system comprising a "first-selector," a "second-selector," and a battery for furnishing the current necessary for operating said "selectors," said "second-selector" having release mechanism operated by a "release-magnet," and a release-circuit in which the said battery and magnet are connected in series, said circuit having a plurality of switch-points whereof two of the same are controlled by said "first-selector," the system also comprising a talking 100 circuit independent of said release-circuit.

45. An automatic telephone system comprising a "first-selector," a "second-selector," and a battery for furnishing the current necessary for operating said "selectors," 105 said "second-selector" having release mechanism operated by a "release-magnet," and a release-circuit in which the said battery and magnet are connected in series, said circuit having a plurality of switch-points controlled by said "first-selector," the system also comprising a talking circuit independent of said release-circuit.

46. An automatic telephone system comprising a "connector," a "selector," and a battery for furnishing the current necessary for operating said "connector" and "selector," said "connector" having release mechanism operated by a "release-magnet," and a release-circuit in which the said battery 125

and magnet are connected in series, said circuit having a plurality of switch-points one of which is controlled by said "selector," the system also comprising a talking circuit 5 independent of said release-circuit.

47. An automatic telephone system comprising a "connector," a "selector," and a battery for furnishing the current necessary for operating said "connector" and "selector," said "connector" having release mechanism operated by a "release-magnet," and a release-circuit in which the said battery and magnet are connected in series, said circuit having a plurality of switch-points 10 whereof two of the same are controlled by said "selector," the system also comprising a talking circuit independent of said release-circuit.

48. An automatic telephone system comprising a "connector," a "selector," and a battery for furnishing the current necessary for operating said "connector" and "selector," said "connector" having release mechanism operated by a "release-magnet," and a release-circuit in which the said battery and magnet are connected in series, said circuit having a plurality of switch-point controlled by said "selector," the system also comprising a talking circuit independent of 25 said release-circuit.

49. An automatic telephone system comprising a "connector," an electrically-propelled and step-by-step-actuated switching machine, and a battery for furnishing the current necessary for operating said "connector" and switching machine, said "connector" having release mechanism operated by a "release-magnet," and a release-circuit 35 in which the said battery and magnet are connected in series, said circuit having a plurality of switch-points one of which is controlled by said machine, the system also comprising a talking circuit independent of 40 said release-circuit.

50. An automatic telephone system comprising a "connector," an electrically-propelled and step-by-step-actuated switching machine, and a battery for furnishing the current necessary for operating said "connector" and switching machine, said "connector" having release mechanism operated by a "release-magnet," and a release circuit 50 in which the said battery and magnet are connected in series, said circuit having a plurality of switch-points whereof two of the same are controlled by said machine, the system also comprising a talking circuit independent of said release-circuit.

51. An automatic telephone system comprising a "connector," an electrically-propelled and step-by-step-actuated switching machine, and a battery for furnishing the current necessary for operating said "connector" and switching machine, said "connector" having release mechanism operated 60

by a "release-magnet," and a release-circuit in which the said battery and magnet are connected in series, said circuit having a plurality of switch-points controlled by said machine, the system also comprising a talking circuit 70 independent of said release-circuit.

52. An automatic telephone system comprising a "selector" provided with a pair of "line-relays" having normally separated contacts, and provided also with release mechanism operated by a "release-magnet," means for supplying all necessary current, and a "release-circuit" including a winding of said magnet, and also including said contacts, together with an electrically-propelled and step-by-step-actuated switching machine having normally open contacts which are likewise included in said "release-circuit".

53. An automatic telephone system comprising first and second "selectors", said "second-selector" being provided with a pair of "line-relays" having normally separated contacts, and provided also with release mechanism operated by a "release-magnet", means for supplying all necessary current, 80 and a "release-circuit" including a winding of said magnet, and also including said contacts, the said "first-selector" having normally open switch-contacts which are likewise included in said "release-circuit".

54. An automatic telephone system comprising an electrically-propelled and step-by-step-actuated switching machine provided with a pair of "line-relays" having normally separated contacts, and provided also with release mechanism operated by a "release-magnet", means for supplying all necessary current, and a "release-circuit" including a winding of said magnet, and also including said contacts, together with an 100 electrically-propelled and step-by-step-actuated switching machine having normally open contacts which are likewise included in said "release-circuit".

55. An automatic telephone system comprising a "selector" provided with a pair of "line-relays" having normally separated contacts, and provided also with release mechanism operated by a "release-magnet", a "line-circuit" from which said relays are 110 normally disconnected, means for supplying all necessary current, a relay adapted when energized to connect the said "line-relays" with the "line-circuit", and a "release-circuit" including a winding of said magnet, 115 and including also said contacts.

56. An automatic telephone system comprising an electrically-propelled and step-by-step-actuated switching machine provided with a pair of line-relays having normally separated contacts, and provided also with release mechanism operated by a "release-magnet", a "line-circuit" from which 125 said relays are normally disconnected, means for supplying all necessary current, a relay 130

adapted when energized to connect the said "line-relays" with the "line-circuit", and a "release-circuit" including a winding of said magnet, and including also said contacts.

57. An automatic telephone system comprising a "selector" having release mechanism operated by a "release-magnet", a pair of "line-relays" having normally separated contacts, means for supplying all necessary current, and a circuit including a winding of said magnet, and including also said contacts, together with a step-by-step switching machine having normally separated contacts which are likewise included in said circuit.

58. An automatic telephone system comprising an electrically-propelled and step-by-step-actuated switching machine having release mechanism operated by a "release-magnet", a pair of "line-relays" having normally separated contacts, means for supplying all necessary current, and a circuit including a winding of said magnet, and including also said contacts, together with another switching machine having normally separated contacts which are likewise included in said circuit.

59. An automatic telephone system comprising a subscriber's line, a "selector" provided with a pair of "line-wipers" normally disconnected from said line, means for supplying all necessary current, a relay adapted when energized to immediately connect the said wipers with the said line, trunks to be selected by said wipers, and means for causing said wipers to skip busy trunks and stop on an idle trunk.

60. An automatic telephone system comprising a subscriber's line, a "selector" provided with a pair of "line-wipers" normally disconnected from said line, means for supplying all necessary current, a relay adapted when energized to immediately connect the said wipers with the said line, suitable means whereby said relay always remains energized during the use of said wipers for talking purposes, trunks to be selected by said wipers, and means for causing said wipers to skip busy trunks and stop on an idle trunk.

61. An automatic telephone system comprising a subscriber's line, a "selector" provided with a pair of "line-wipers" normally disconnected from said line, means for supplying all necessary current, and a relay adapted when energized to immediately connect the said wipers with the said line, together with suitable means whereby said relay always remains energized during the use of said wipers for talking purposes, and a pair of "line-relays" normally connected with the said line but adapted to be disconnected therefrom by the energizing of said relay.

62. An automatic telephone system comprising a pair of metallic "line-circuit-conductors", a "selector" provided with a pair

of "line-wipers" normally disconnected from said conductors, means for supplying all necessary current, a relay adapted when energized to immediately connect the said wipers with the said conductors, trunks to be selected by said wipers, and means for causing said wipers to skip busy trunks and stop on an idle trunk.

63. An automatic telephone system comprising a pair of metallic "line-circuit-conductors", a "selector" provided with a pair of "line-wipers" normally disconnected from said conductors, means for supplying all necessary current, a relay adapted when energized to immediately connect the said wipers with the said conductors, suitable means whereby said relay always remains energized during the use of said wipers for talking purposes, trunks to be selected by said wipers, and means for causing said wipers to skip busy trunks and stop on an idle trunk.

64. An automatic telephone system comprising a pair of metallic "line-circuit-conductors", a "selector" provided with a pair of "line-wipers" normally disconnected from said conductors, means for supplying all necessary current, and a relay adapted when energized to immediately connect the said wipers with the said conductors, together with suitable means whereby said relay always remains energized during the use of said wipers for talking purposes, and a pair of "line-relays" normally connected with the said conductors but adapted to be disconnected therefrom by the energizing of said relay.

65. In an automatic telephone exchange system, the combination of a subscriber's line, a "selector" provided with a pair of "line-wipers" normally disconnected from said line, a third wiper, means for supplying all necessary current, a release-relay, and a relay adapted when energized to immediately connect the said line-wipers with the said line, the said release-relay being provided with an energizing circuit including said third wiper and having normally open and normally closed switch-points.

66. In an automatic telephone exchange system, the combination of a subscriber's line, a "selector" provided with a pair of "line-wipers" normally disconnected from said line, a third wiper, means for supplying all necessary current, a release-relay, and a relay adapted when energized to immediately connect the said line-wipers with the said line, together with suitable means whereby said relay always remains energized during the use of said wipers for talking purposes, the said release-relay being provided with an energizing circuit including said third wiper and having normally open and normally closed switch-points.

67. In an automatic telephone exchange

system, the combination of a subscriber's line, a "selector" provided with a pair of "line-wipers" normally disconnected from said line, means for supplying all necessary current, and a relay adapted when energized to immediately connect the said wipers with the said line, together with suitable means whereby said relay always remains energized during the use of said wipers for talking purposes, and a pair of "line-relays" normally connected with the said line but adapted to be disconnected therefrom by the energizing of said relay, the said relay being provided with an energizing circuit having normally open and normally closed switch-points.

68. In an automatic telephone exchange system, the combination of a pair of metallic "line-circuit-conductors," a "selector" provided with a pair of "line-wipers" normally disconnected from said conductors, a third wiper, means for supplying all necessary current, a release-relay, and a relay adapted when energized to immediately connect the said line-wipers with the said conductors, the said release-relay being provided with an energizing circuit including said third wiper and having normally open and normally closed switch-points.

69. In an automatic telephone exchange system, the combination of a pair of metallic "line-circuit-conductors," a "selector" provided with a pair of "line-wipers" normally disconnected from said conductors, a third wiper, means for supplying all necessary current, a release-relay, and a relay adapted when energized to immediately connect the said line-wipers with the said conductors, together with suitable means whereby said relay always remains energized during the use of said wipers for talking purposes, the said release-relay being provided with an energizing circuit including said third wiper and having normally open and normally closed switch-points.

70. In an automatic telephone exchange system, the combination of a pair of metallic "line-circuit-conductors," a "selector" provided with a pair of "line-wipers" normally disconnected from said conductors, means for supplying all necessary current, and a relay adapted when energized to immediately connect the said wipers with the said conductors, together with suitable means whereby said relay always remains energized during the use of said wipers for talking purposes, and a pair of "line-relays" normally connected with the said conductors but adapted to be disconnected therefrom by the energizing of said relay, the said relay being provided with an energizing circuit having normally open and normally closed switch-points.

71. An automatic telephone system comprising a "selector" provided with a rotat-

able and endwise-movable switch-shaft, an electro-magnet provided with means for giving the shaft an endwise step-by-step motion, a second electro-magnet combined with means for giving the shaft a step-by-step rotary motion, means for temporarily locking the shaft in its various operative positions, a release mechanism operated by a "release-magnet," whereby the said shaft may be restored to its normal position, means for supplying all necessary current, normally closed contacts adapted to be separated immediately upon the energizing of said "release-magnet," and a normally open energizing circuit for said electro-magnet by which the shaft is given an endwise movement, said circuit including said contacts.

72. An automatic telephone system comprising a "selector" provided with a rotatable and endwise-movable switch-shaft, an electro-magnet combined with means for giving the shaft an endwise step-by-step movement, a second electro-magnet combined with means for giving the shaft a step-by-step rotary motion, suitable means for temporarily locking or maintaining the shaft in any of its various operative positions, a release mechanism operated by a "release-magnet," whereby the said shaft can be restored to its normal position, means for supplying all necessary current, normally closed switch-contacts adapted to be opened or separated immediately upon the energizing of said "release-magnet," a so-called "private-magnet," a normally open energizing circuit for the electro-magnet by which the shaft is rotated, said circuit being controlled by said "private-magnet," and means whereby the said contacts and a winding of said "private-magnet" are connected in a normally open energizing circuit for the latter.

73. An automatic telephone system comprising a "selector" provided with a rotatable and endwise-movable switch-shaft, an electro-magnet provided with means for giving the shaft an endwise step-by-step motion, a second electro-magnet combined with means for giving the shaft a step-by-step rotary motion, means for temporarily locking the shaft in its various operative positions, a release mechanism operated by a "release-magnet," whereby the said shaft may be restored to its normal position, means for supplying all necessary current, normally closed contacts adapted to be separated immediately upon the energizing of said "release-magnet," and a normally open energizing circuit for said electro-magnet by which the shaft is given an endwise movement, said circuit including said contacts, there being also a pair of "line-relays" provided with suitable contacts and connections for controlling the circuits of said electro-magnets.

74. An automatic telephone system comprising a "selector" provided with a rotatable and endwise-movable switch-shaft, an electro-magnet combined with means for giving the shaft an endwise step-by-step movement, a second electro-magnet combined with means for giving the shaft a step-by-step rotary motion, suitable means for temporarily locking or maintaining the shaft in any of its various operative positions, a release mechanism operated by a "release-magnet", whereby the said shaft can be restored to its normal position, means for supplying all necessary current, normally closed switch-contacts adapted to be opened or separated immediately upon the energizing of said "release-magnet", a so-called "private-magnet", a normally open energizing circuit for the electro-magnet by which the shaft is rotated, said circuit being controlled by said "private-magnet", and means whereby the said contacts and a winding of said "private-magnet" are connected in a normally open energizing circuit for the latter, together with a "release-relay" provided with normally open switch-contacts for controlling an energizing circuit including a winding of said "release-magnet".

75. In an automatic telephone exchange system, the combination of a "selector" provided with a rotatable and endwise-movable switch-shaft, an electro-magnet provided with means for giving the shaft an endwise step-by-step motion, a second electro-magnet combined with means for giving the shaft a step-by-step rotary motion, means for temporarily locking the shaft in its various operative positions, a release mechanism operated by a "release-magnet", whereby the said shaft may be restored to its normal position, means for supplying all necessary current, normally closed contacts adapted to be separated immediately upon the energizing of said "release-magnet", a so-called "private-magnet", a normally open energizing circuit for the electro-magnet by which the shaft is given an endwise movement, said circuit including said contacts, there being also a pair of "line-relays" provided with suitable contacts and connections for controlling the circuits of said electro-magnets, together with a "release-relay" provided with normally open switch-contacts for controlling an energizing circuit including a winding of said "release-magnet".

76. In an automatic telephone exchange system, the combination of a "selector" provided with a rotatable and endwise-movable switch-shaft, an electro-magnet combined with means for giving the shaft an endwise step-by-step movement, a second electro-magnet combined with means for giving the shaft a step-by-step rotary motion, suitable means for temporarily locking or maintaining the shaft in any of its various operative positions, a release mechanism operated by a "release-magnet", whereby the said shaft can be restored to its normal position, means for supplying all necessary current, normally closed switch-contacts adapted to be opened or separated immediately upon the energizing of said "release-magnet", a so-called "private-magnet", a normally open energizing circuit for the electro-magnet by which the shaft is rotated, said circuit being controlled by said "private-magnet", and means whereby the said contacts and a winding of said "private-magnet" are connected in a normally open energizing circuit for the latter, together with a "release-relay" provided with normally open switch-contacts for controlling an energizing circuit including a winding of said "release-magnet".

means for supplying all necessary current, normally closed switch-contacts adapted to be opened or separated immediately upon the energizing of said "release-magnet", a so-called "private-magnet", a normally open energizing circuit for the electro-magnet by which the shaft is rotated, said circuit being controlled by said "private-magnet", and means whereby the said contacts and a winding of said "private-magnet" are connected in a normally open energizing circuit for the latter, together with a "release-relay" provided with normally open switch-contacts for controlling an energizing circuit including a winding of said "release-magnet".

77. In an automatic telephone exchange system, the combination of a "selector" provided with a rotatable and endwise-movable switch-shaft, an electro-magnet provided with means for giving the shaft an endwise step-by-step motion, a second electro-magnet combined with means for giving the shaft a step-by-step rotary motion, means for temporarily locking the shaft in its various operative positions, a release mechanism operated by a "release-magnet", whereby the said shaft may be restored to its normal position, means for supplying all necessary current, normally closed contacts adapted to be separated immediately upon the energizing of said "release-magnet", a normally open energizing circuit for said electro-magnet by which the shaft is given an endwise movement, said circuit including said contacts, there being also a pair of "line-relays" provided with suitable contacts and connections for controlling the circuits of said electro-magnets, together with a "release-relay" provided with normally open switch-contacts for controlling an energizing circuit including a winding of said "release-magnet".

78. In an automatic telephone exchange system, the combination of a "selector" provided with a rotatable and endwise-movable switch-shaft, an electro-magnet combined with means for giving the shaft an endwise step-by-step movement, a second electro-magnet combined with means for giving the shaft a step-by-step rotary motion, suitable means for temporarily locking or maintaining the shaft in any of its various operative positions, a release mechanism operated by a "release-magnet", whereby the said shaft can be restored to its normal position, means for supplying all necessary current, normally closed switch-contacts adapted to be opened or separated immediately upon the energizing of said "release-magnet", a so-called "private-magnet", a normally open energizing circuit for the electro-magnet by which the shaft is rotated, said circuit being controlled by said "private-magnet", and means whereby the said contacts and a winding of said "private-magnet" are connected in a normally open energizing circuit for the latter, together with a "release-relay" provided with normally open switch-contacts for controlling an energizing circuit including a winding of said "release-magnet".

winding of said "private-magnet" are connected in a normally open energizing circuit for the latter, there being also a pair of "line-relays" provided with suitable contacts and connections for controlling the circuits of said electro-magnets, together with a "release-relay" provided with normally open switch-contacts for controlling an energizing circuit including a winding of said "release-magnet".

79. In an automatic telephone exchange system, the combination of a "selector" provided with a rotatable and endwise-movable switch-shaft, an electro-magnet provided with means for giving the shaft an endwise step-by-step motion, a second electro-magnet combined with means for giving the shaft a step-by-step rotary motion, means for temporarily locking the shaft in its various operative positions, a release mechanism operated by a "release-magnet", whereby the said shaft may be restored to its normal position, means for supplying all necessary current, normally closed contacts adapted to be separated immediately upon the energizing of said "release-magnet", and a normally open energizing circuit for said electro-magnet by which the shaft is given an endwise movement, said circuit including said contacts, and normally open switch-contacts adapted to be closed by the initial endwise movement of the said shaft and included in the energizing circuit of the said electro-magnet by which the shaft is rotated.

80. In an automatic telephone exchange system, the combination of a "selector" provided with a rotatable and endwise-movable switch-shaft, an electro-magnet combined with means for giving the shaft an endwise step-by-step movement, a second electro-magnet combined with means for giving the shaft a step-by-step rotary motion, suitable means for temporarily locking or maintaining the shaft in any of its various operative positions, a release mechanism operated by a "release-magnet", whereby the said shaft can be restored to its normal position, means for supplying all necessary current, normally closed switch-contacts adapted to be opened or separated immediately upon the energizing of said "release-magnet", a so-called "private-magnet", a normally open energizing circuit for the electro-magnet by which the shaft is rotated, said circuit being controlled by said "private-magnet", and means whereby the said contacts and a winding of said "private-magnet" are connected in a normally open energizing circuit for the latter, there being also a pair of "line-relays" provided with suitable contacts and connections for controlling the circuits of said electro-magnets, and normally open switch-contacts adapted to be closed by the initial endwise movement of the said shaft and included in the energizing circuit of the said electro-magnet by which the shaft is rotated.

81. In an automatic telephone exchange

system, the combination of a "selector" provided with a rotatable and endwise-movable switch-shaft, an electro-magnet provided with means for giving the shaft an endwise step-by-step motion, a second electro-magnet combined with means for giving the shaft a step-by-step rotary motion, means for temporarily locking the shaft in its various operative positions, a release mechanism operated by a "release-magnet", whereby the said shaft may be restored to its normal position, means for supplying all necessary current, normally closed contacts adapted to be separated immediately upon the energizing of said "release-magnet", and a normally open energizing circuit for said electro-magnet by which the shaft is given an endwise movement, said circuit including said contacts, there being also a pair of "line-relays" provided with suitable contacts and connections for controlling the circuits of said electro-magnets, and normally open switch-contacts adapted to be closed by the initial endwise movement of the said shaft and included in the energizing circuit of the said electro-magnet by which the shaft is rotated.

82. In an automatic telephone exchange system, the combination of a "selector" provided with a rotatable and endwise-movable switch-shaft, an electro-magnet combined with means for giving the shaft an endwise step-by-step movement, a second electro-magnet combined with means for giving the shaft a step-by-step rotary motion, suitable means for temporarily locking or maintaining the shaft in any of its various operative positions, a release mechanism operated by a "release-magnet", whereby the said shaft can be restored to its normal position, means for supplying all necessary current, normally closed switch-contacts adapted to be opened or separated immediately upon the energizing of said "release-magnet", a so-called "private-magnet", a normally open energizing circuit for the electro-magnet by which the shaft is rotated, said circuit being controlled by said "private-magnet", and means whereby the said contacts and a winding of said "private-magnet" are connected in a normally open energizing circuit for the latter, there being also a pair of "line-relays" provided with suitable contacts and connections for controlling the circuits of said electro-magnets, and normally open switch-contacts adapted to be closed by the initial endwise movement of the said shaft and included in the energizing circuit of the said electro-magnet by which the shaft is rotated.

83. In an automatic telephone exchange system, the combination of a "selector" provided with a rotatable and endwise-movable switch-shaft, an electro-magnet provided with means for giving the shaft an endwise

step-by-step motion, a second electro-magnet combined with means for giving the shaft a step-by-step rotary motion, means for temporarily locking the shaft in its various operative positions, a release mechanism operated by a "release-magnet", whereby the said shaft may be restored to its normal position, means for supplying all necessary current, normally closed contacts adapted to be separated immediately upon the energizing of said "release-magnet", and a normally open energizing circuit for said electro-magnet by which the shaft is given an endwise movement, said circuit including said contacts, together with a "release-relay" provided with normally open switch-contacts for controlling an energizing circuit including a winding of said "release-magnet", and normally open switch-contacts adapted to be closed by the initial endwise movement of the said shaft and included in the energizing circuit of the said electro-magnet by which the shaft is rotated.

84. In an automatic telephone exchange system, the combination of a "selector" provided with a rotatable and endwise-movable switch-shaft, an electro-magnet combined with means for giving the shaft an endwise step-by-step movement, a second electro-magnet combined with means for giving the shaft a step-by-step rotary motion, suitable means for temporarily locking or maintaining the shaft in any of its various operative positions, a release mechanism operated by a "release-magnet", whereby the said shaft can be restored to its normal position, means for supplying all necessary current, normally closed switch-contacts adapted to be opened or separated immediately upon the energizing of said "release-magnet", a so-called "private-magnet", a normally open energizing circuit for the electro-magnet by which the shaft is rotated, said circuit being controlled by said "private-magnet", and means whereby the said contacts and a winding of said "private-magnet" are connected in a normally open energizing circuit for the latter, together with a "release-relay" provided with normally open switch-contacts for controlling an energizing circuit including a winding of said "release-magnet", and normally open switch-contacts adapted to be closed by the initial endwise movement of the said shaft and included in the energizing circuit of the said electro-magnet by which the shaft is rotated.

85. In an automatic telephone exchange system, the combination of a "selector" provided with a rotatable and endwise-movable switch-shaft, an electro-magnet provided with means for giving the shaft an endwise step-by-step motion, a second electro-magnet combined with means for giving the shaft a step-by-step rotary motion, means for temporarily locking the shaft in

its various operative positions, a release mechanism operated by a "release-magnet", whereby the said shaft may be restored to its normal position, means for supplying all necessary current, normally closed contacts 70 adapted to be separated immediately upon the energizing of said "release-magnet", and a normally open energizing circuit for said electro-magnet by which the shaft is given an endwise movement, said circuit including said contacts, there being also a pair of "line-relays" provided with suitable contacts and connections for controlling the circuits of said electro-magnets, together with a "release-relay" provided with normally 75 open switch-contacts for controlling an energizing circuit including a winding of said "release-magnet", and normally open switch-contacts adapted to be closed by the initial endwise movement of the said shaft 80 and included in the energizing circuit of the said electro-magnet by which the shaft is rotated.

86. In an automatic telephone exchange system, the combination of a "selector" provided with a rotatable and endwise-movable switch-shaft, an electro-magnet combined with means for giving the shaft an endwise step-by-step movement, a second electro-magnet combined with means for giving the shaft a step-by-step rotary motion, suitable means for temporarily locking or maintaining the shaft in any of its various operative positions, a release mechanism operated by a "release-magnet", whereby the said shaft can be restored to its normal position, means for supplying all necessary current, normally closed switch-contacts adapted to be opened or separated immediately upon the energizing of said "release-magnet", a so-called "private-magnet", a normally open energizing circuit for the electro-magnet by which the shaft is rotated, said circuit being controlled by said "private-magnet", and means whereby the said contacts and a winding of said "private-magnet" are connected in a normally open energizing circuit for the latter, there being also a pair of "line-relays" provided with suitable contacts and connections for controlling the circuits of said electro-magnets, together with a "release-relay" provided with normally 90 open switch-contacts for controlling an energizing circuit including a winding of said "release-magnet", and normally open switch-contacts adapted to be closed by the initial 95 endwise movement of the said shaft 100 and included in the energizing circuit of the said electro-magnet by which the shaft is rotated.

87. An automatic telephone system comprising a "selector" provided with release mechanism operated by a "release-magnet", and having a "release-relay" for controlling the energizing of said "release-magnet", to- 105 110 115 120 125 130

gether with a so-called "private-magnet" provided with normally closed switch-contacts, means for supplying all necessary current, and an energizing circuit for said "release-relay" including the said normally closed contacts of the "private-magnet".

88. An automatic telephone system comprising a line, a bridge on the line, a "selector" having a rotatable and endwise-movable switch-shaft, electro-magnetically-actuated mechanism for operating said shaft, a bridge-cut-off and line-switching relay, means for supplying all necessary current, and a normally open circuit for said relay, together with normally closed switch-contacts included in said circuit, and means whereby the said contacts are opened by the initial endwise movement of the shaft, and then reclosed as soon as the said shaft starts to rotate.

89. An automatic telephone system comprising a "selector" provided with a switch-shaft, electro-magnets combined with means for giving said shaft a step-by-step endwise movement, as well as a step-by-step rotary motion, means for supplying all necessary current, a normally-open energizing circuit for the magnet by which the shaft is rotated, and normally open switch-contacts included in said circuit, together with means whereby said contacts are closed by the initial endwise movement of said shaft.

90. An automatic telephone system comprising a line, a bridge on the line, a "selector" provided with a rotatable and endwise-movable switch-shaft, a bridge-cut-off and line-switching relay, electro-magnetically-actuated mechanism for operating said shaft, means for supplying all necessary current, an energizing circuit for said relay, normally closed contacts in said circuit, and means whereby said contacts remain closed throughout the entire range of vertical movement on the part of said shaft, but whereby said contacts are opened as soon as the said shaft starts to rotate.

91. An automatic telephone system comprising a line, a bridge on the line, a "selector" provided with a rotatable and endwise-movable switch-shaft, a bridge-cut-off and line-switching relay, electro-magnetically-actuated mechanism for operating said shaft, means for supplying all necessary current, an energizing circuit for said relay, normally open contacts in said circuit, and means whereby said contacts remain open throughout the entire range of vertical movement on the part of said shaft, but whereby said contacts are closed as soon as the said shaft starts to rotate.

92. An automatic telephone system comprising a "selector" provided with a rotatable and endwise-movable switch-shaft, a "private-wiper" and a pair of "line-wipers" on said shaft, means for giving the shaft

a step-by-step endwise movement, a so-called "rotary-magnet" combined with means for giving the shaft a step-by-step rotary motion, a so-called "private-magnet", a pair of normally separated contacts operated by 70 said "private-magnet", a battery for supplying current, a normally open circuit in which said battery and normally open contacts and "rotary-magnet" are connected in series, another pair of normally open contacts operated by said "private-magnet", an energizing circuit for said "private-magnet" including the contacts of the said "line-relay", and a second energizing circuit for said "private-magnet" including the said "private-wiper" and the said second or last-mentioned pair of normally open contacts operated by the "private-magnet".

93. An automatic telephone system comprising a "selector" provided with a "release-relay" and a so-called "private-magnet", means for supplying all necessary current, a so-called "private-switch-wiper", and a normally open circuit in which said relay, magnet and wiper are connected in series, the resistance of the relay and magnet being of such character that only the magnet will become energized when the two are thus connected in series.

94. An automatic telephone system comprising a "selector" provided with a so-called "rotary-magnet" having means for automatically opening and closing its own circuit, a relay adapted when energized to close an energizing circuit including a winding of the said "rotary-magnet", means whereby the "rotary-magnet" is operative to vibrate the armature of the said relay, a normally open energizing circuit for said relay which excludes the contacts of the latter, and another energizing circuit for the same which includes normally open contacts of the relay, together with means for furnishing all necessary current.

95. An automatic telephone system comprising first and second "selectors", each "selector" being provided with a pair of "line-relays", a "release-relay" and a release mechanism operated by a "release-magnet", and means for supplying all necessary current, together with suitable connections whereby the "release-magnet" of either "selector" may be energized by the energizing of either the "line-relays" or the "release-relay" of the "selector" to which the "release-magnet" is allotted, and whereby the energizing of the "release-relay" of the "second-selector" will, when the two "selectors" are connected together, connect the "release-magnet" of the "second-selector" in series 110 with the "release-relay" of the "first-selector".

96. An automatic telephone system comprising a "selector" provided with a "release-relay", a "release-magnet" controlled 130

by said "release-relay", and release mechanism operated by said "release-magnet", means for supplying all necessary current, normally closed contacts also operated by said "release-magnet", a so-called "private-magnet", and a normally open circuit including said relay and "private-magnet" and normally closed contacts, but the said "private-magnet" being of such high resistance that the said relay will not become operatively energized when the two are thus connected in series.

97. An automatic telephone system comprising a "selector" provided with a "release-relay", a "rotary-magnet" and a so-called "private-magnet", four switch-contacts operated by said "private-magnet", two of said contacts being normally closed together, and the other two contacts being normally out of engagement respectively with one or the other of said normally closed contacts, means for supplying all necessary current, an energizing circuit for said "release-relay" including the contacts which are normally closed together, an energizing circuit for said "rotary-magnet" including one pair of the normally separated contacts, and an energizing circuit for said "private-magnet" including the other pair of normally separated contacts.

98. An automatic telephone system comprising a line, a bridge on the line, a "selector" provided with a rotatable and endwise-movable switch-shaft, a combined bridge-cut-off and line-switching relay, normally separated and normally closed contacts operated by the said switch-shaft, said contacts being adapted to retain their normal condition throughout the entire range of endwise movement on the part of said shaft, but adapted to reverse their normal condition as soon as the shaft starts to rotate, means for supplying all necessary current, and an energizing circuit for said relay, said circuit having parallel branches whereof one includes the normally closed contacts and the other the normally open contacts.

99. An automatic telephone system comprising a "selector" provided with a pair of "line-relays" which are normally disconnected from the "line-circuit", a third relay for controlling the connection between the "line-circuit" and the said "line-relays", a release mechanism operated by a "release-magnet", means for supplying all necessary current, an energizing circuit for said "release-magnet" controlled by said "line-relays", together with automatic means for retaining the energizing condition of said third relay until the "selector" makes connection with some other switching machine, and whereby the said "line-relays" can be employed for energizing said "release-mag-

net" and thereby effecting a release at any time before connection with another switching machine is established.

100. An automatic telephone system comprising a "selector" provided with switching means operated by a so-called "rotary-magnet", and with release mechanism operated by a "release-magnet", normally closed contacts operated by said "release-magnet", means for supplying all necessary current, and an energizing circuit for said "rotary-magnet" including said contacts.

101. An automatic telephone system comprising first-selectors provided with line-wipers, lines normally disconnected from said line-wipers, second-selectors provided with line-wipers, lines normally connected with the said wipers of the second-selectors, and connectors, together with subscriber-operated switches for causing the said first and second selectors to perform trunking operations corresponding to the first and second digits of any called number, and the connector to perform a line-connecting switching operation corresponding to the third and fourth digits of the called number.

102. In a telephone system, a trunk-selecting switch mechanism provided with a rotatable and vertically movable switch-shaft, normally open and normally closed circuit-controlling contacts adapted to be operated by the switch-shaft at any level thereof, and trunks to be selected by the movements of said shaft.

103. In a telephone exchange system, the combination of a telephone line, a line-relay to be cut off from the line, a cut-off-relay, automatic means for energizing the cut-off-relay when the line calls, controlled by the calling subscriber, and automatic means for energizing the cut-off-relay when the line is called.

104. In a telephone exchange system, the combination of a telephone line, a pair of bridged line-relays, a trunk-line, automatic means for connecting the telephone line with the trunk-line, a bridge-cut-off-relay, and automatic means for energizing said cut-off-relay simultaneously with the establishment of connection with the trunk-line.

105. In a telephone exchange system, the combination of a telephone line, a line-relay to be cut off from the line, means to be switched into and out of connection with the telephone line, a combined cut-off and line-switching relay, means for energizing said cut-off-relay when the line calls, controlled by the calling subscriber, and means for energizing the cut-off-relay when the line is called.

106. In a telephone exchange system, the combination of a line, a switch provided with a line-relay allotted to and normally

disconnected from the line, automatic means for connecting the relay with the line, controlled by the calling subscriber, a circuit for energizing said line relay, said energizing circuit including a voice-current conductor of said line, a local operating circuit controlled by said line relay, and an operating magnet in said local circuit for effecting the initial operation of said switch.

107. In a telephone exchange system, the combination of a line, trunk lines, a line-relay allotted to the line, means controlled by the line-relay, adapted for connecting the line with an idle trunk-line, said line-relay normally disconnected from said line, and automatic means for connecting the relay with the line when connection is to be established with a trunk-line, controlled by the calling subscriber.

108. In a telephone exchange system, the combination of a line, a bridge for said line, a bridge-cut-off-relay, means for energizing said cut-off relay, means for de-energizing said relay to cut off the bridge, trunks or trunk-lines, a relay in said bridge, and trunk-selecting mechanism controlled by said relay.

109. In a telephone exchange system, the combination of a line, trunk-lines, trunk-selecting switch mechanism for connecting the line with an idle trunk-line, a line-relay for controlling said mechanism, allotted to the said line and normally disconnected therefrom, a cut-off-relay, means for energizing said cut-off-relay to place the line-relay in connection with the said line, and means for de-energizing said cut-off-relay to disconnect the line-relay from said line.

110. In a telephone exchange system, the combination of trunk-lines, an automatic trunk-selecting switch mechanism normally operative to receive electrical impulses, another automatic trunk-selecting switch mechanism normally inoperative to receive electrical impulses, means for transmitting electrical impulses to said normally operative mechanism, and means allotted to said normally inoperative mechanism and controlled by said normally operative mechanism, adapted to render the said normally inoperative mechanism operative to receive electrical impulses from the said transmitting means.

111. In a telephone exchange system, the combination of an automatic switch normally operative to receive switch-operating electrical impulses, another automatic switch normally inoperative to receive switch-operating electrical impulses, and means allotted to said normally inoperative switch and controlled by said normally operative switch, adapted to place the said normally inoperative switch in operative condition to

receive switch-operating electrical impulses, 65 together with means for first transmitting electrical impulses to the normally operative switch and then to the normally inoperative switch.

112. In a telephone exchange system, the combination of a line, another line, an automatic switch normally in operative relation to said first line and adapted for automatically connecting the two lines together, another automatic switch normally in non-operative relation to said second line, a third line to be connected with the second line by the said normally inoperative switch, and means allotted to the normally inoperative switch for placing the same in operative relation to said second line, said means controlled by said normally operative switch.

113. In a telephone exchange system, a line composed of two parallel conductors, an automatic switch normally in non-operative relation to said line, a third conductor parallel with said line-conductors, means controlled over said third conductor for placing said switch in operative relation to said line, means for closing a circuit over said third conductor to place the switch in operative relation to the line, and means for then transmitting electrical impulses over said line to operate said switch.

114. In a telephone exchange system, the combination of a bank of contacts, trunks leading from said contacts, movable wipers for said contacts, vertical and rotary and private magnets for controlling the operation of said wipers, release mechanism, a release-magnet, energizing circuits for all of said magnets, said release-magnet controlling the three circuits of the other magnets.

115. In a telephone exchange system, the combination of a line, a bank of contacts, trunks leading from said contacts, a pair of selector-line-wipers normally disconnected from said line, means for moving said wipers over said contacts, means for supplying all necessary current, a suitable relay, an energizing circuit for said relay, means by which the wipers are connected with the line as soon as the relay is energized, and means for closing said circuit to energize 110 the relay simultaneously with the seizure of an idle trunk by said wipers.

116. In a telephone exchange system, the combination of a line, a bank of contacts, trunks leading from said contacts, a pair of selector-line-wipers normally disconnected from said line, means for moving said wipers over said contacts, means for supplying all necessary current, a suitable relay, an energizing circuit for said relay, means by which the wipers are connected with the line as soon as the relay is energized, means for closing said circuit to energize the relay si-

multaneously with the seizure of an idle trunk by said wipers, a pair of line-relays normally connected with said line, and contacts by which the said first-mentioned relay disconnects the line-relays from the line simultaneously with the seizure of an idle trunk by said wipers.

117. A telephone exchange system comprising automatic means for trunking between the subscribers thereof, provided with electromagnets for releasing purposes, and trunk-release circuits each including a plurality of said magnets in series, a magnet of one of said circuits controlling another of said circuits.

118. A telephone exchange system comprising a plurality of automatic switches each having an electromagnet for release purposes, trunk-connection between said switches, means for successively operating said switches to close said trunk connection and thereby extend connection in the direction of the called subscriber, and a trunk-release circuit closed by one of said switches including said magnets in series.

119. A telephone exchange system comprising automatic means for trunking between the subscribers thereof, provided with electromagnets for releasing purposes, trunk-release circuits each including a plurality of said magnets in series, and line-relays for closing said release circuits.

120. A telephone exchange system comprising a plurality of automatic switches each having an electromagnet for release purposes, trunk-connection between said switches, means for successively operating said switches to extend connection in the direction of the called subscriber, and a trunk-release circuit including said magnets in series, one of said automatic switches being provided with a pair of line-relays for closing the trunk-release circuit through all of the switches.

121. In a telephone system, a calling line, a called line, automatic means for extending a call from a calling to a called line, said means including a line relay, switching means controlled by said relay, a cut-off relay, means controlled over the calling line and from the substation thereof for operating said cut-off relay to disconnect by a single movement the line relay before the call reaches the called line, and a talking circuit controlled by said cut-off relay and closed thereat by the same act which cuts off the line relay.

122. A telephone system comprising a calling line, a called line, automatic means for extending a call from a calling to a called line, a bridge including an electromagnetic switch-operating element on the calling line, a bridge-cut-off relay, means controlled over the calling line and from the

substation thereof for operating said cut-off relay to open by a single movement said bridge before the call reaches the called line, and a talking circuit controlled by said cut-off relay and closed thereat by the same act which cuts off said bridge.

123. In a telephone system, a trunk-line, a called line, a calling line, automatic means for extending a call from a calling to a called line, said means including a line relay, switching means controlled by said relay, a cut-off relay, means controlled over the trunk-line for operating said cut-off relay to disconnect by a single movement the line relay before the call reaches the called line, and a talking circuit controlled by said cut-off relay and closed thereat by the same act which cuts off said line relay.

124. A telephone system comprising a calling line, a called line, automatic means for extending a call from a calling to a called line, said means including a trunk-line, a bridge on the trunk-line including an electromagnetic switch-operating element, a bridge-cut-off relay, means controlled over the trunk-line for operating said relay to open by a single movement said bridge before the call reaches the called line, and a talking circuit controlled by said bridge-cut-off relay and closed thereat by the same act which cuts off said bridge.

125. In a telephone system, means for establishing a talking circuit between a calling and a called subscriber's line, said means including an automatic trunk selecting switch for selecting idle trunks and a single-wound relay for controlling said circuit, and means by which the calling subscriber energizes said relay before the call reaches the called line to maintain the continuity of the circuit during use of the same for talking purposes.

126. In a telephone system, a talking circuit, switches for establishing said circuit, a series of bridges including an electromagnetic switch-operating element across the conductors of said circuit, a series of bridge-cut-off relays successively controlled by the calling subscriber for cutting off some of said bridges, a trunk-release circuit and releasing devices controlled thereby, and means in the remaining bridge or bridges for controlling said trunk-release circuit, each bridge-cut-off relay adapted by a single stroke of its armature to open the bridge allotted thereto.

127. A telephone system comprising a talking circuit, means including automatic switches for establishing said circuit, a bridge including an electromagnetic switch-operating element across said circuit, a bridge-cut-off relay controlling said bridge, a trunk-line, automatic means for energizing said relay by the establishment of connec-

tion to said trunk-line, and automatic means for de-energizing said relay in the establishment of connection from said trunk-line.

128. A telephone system comprising a trunk-line, a line-switching relay therefor, automatic means for establishing connections to and from said trunk line, automatic means for energizing said relay by the establishment of a connection to said trunk-line, and automatic means for de-energizing said relay in the establishment of a connection from said trunk-line.

129. A telephone exchange system divided into groups comprising a talking circuit and automatic means for trunking between the subscribers thereof, having vertical motion to select groups and rotary motion to find an idle trunk in any selected group, provided with electromagnets for releasing purposes, and trunk-release circuits each including a plurality of said magnets in series, said circuits being independent of the talking circuit.

130. A telephone exchange system divided into groups comprising a talking circuit and a plurality of automatic switches having vertical motion to select groups and rotary motion to find an idle trunk in any selected group, each having an electromagnet for release purposes, trunk-connection between said switches, means for successively operating said switches to extend connection in the direction of the called subscriber, and a trunk-release circuit including said magnets in series, said circuits being independent of the talking circuit.

131. A telephone exchange system divided into groups comprising automatic means for trunking between the subscribers thereof, having vertical motion to select groups and rotary motion to find an idle trunk in any selected group, provided with electromagnets for releasing purposes, trunk-release circuits each including a plurality of said magnets in series, and line relays for closing said release circuits.

132. A telephone exchange system divided into groups comprising a plurality of automatic switches having vertical motion to select groups and rotary motion to find an idle trunk in any selected group, each having an electromagnet for release purposes, trunk connection between said switches, means for successively operating said switches to extend connection in the direction of the called subscriber, and a trunk-release circuit including said magnets in series, one of said automatic switches being provided with a pair of line relays for closing the trunk-release circuit through all of the switches.

133. In a telephone system divided into groups, a calling line, a called line, means for extending a connection from a calling to a

called subscriber's line, said means including line relays, means having vertical motion to select groups and rotary motion to find an idle trunk in any selected group, controlled by said relays, a cut-off relay, and means controlled over the calling line from the substation thereof for operating said cut-off relay to disconnect by a single movement the line relays before the call reaches the called line.

134. In a telephone system divided into groups, a trunk line, a called line, a calling line, means for extending a connection from a calling to a called subscriber's line, said means including line relays, means having vertical motion to select groups and rotary motion to find an idle trunk in any selected group, controlled by said relays, a cut-off relay, and means controlled over the trunk-line for operating said cut-off relay to disconnect by a single movement the line relays before the call reaches the called line.

135. In a telephone system divided into groups, a calling line, a called line, means for extending a connection from a calling to a called subscriber's line, said means including line relays, means having vertical motion to select groups and rotary motion to find an idle trunk in any selected group, controlled by said relays, a cut-off relay, means controlled over the calling line and from the substation thereof for operating said cut-off relay to disconnect by a single movement the line relays before the call reaches the called line, and a talking circuit controlled by said cut-off relay and closed thereat by the same act which cuts off the line relays.

136. In a telephone system divided into groups, a trunk line, a called line, a calling line, means for extending a connection from a calling to a called subscriber's line, said means including line relays, means controlled by said relays having vertical motion to select groups and rotary motion to find an idle trunk in any selected group, a cut-off relay, means controlled over the trunk line for operating said cut-off relay to disconnect by a single movement the line relays before the call reaches the called line, and a talking circuit controlled by said cut-off relay and closed thereat by the same act which cuts off the bridge.

137. A telephone system divided into groups comprising a calling line, a called line, means for extending a connection from a calling to a called subscriber's line, said means including a trunk line, a bridge on the trunk line including an electromagnetic switch-operating element, means having vertical motion to select groups and rotary motion to find an idle trunk in any selected group, controlled by said bridge, a bridge-cut-off relay, means controlled over the trunk

line for operating said relay to open by a single movement said bridge before the call reaches the called line, and a talking circuit controlled by said bridge-cut-off relay and closed thereat by the same act which cuts off the bridge.

138. In a telephone system divided into groups, means having vertical motion to select groups and rotary motion to find an idle trunk in any selected group, a talking circuit, a relay having contact springs for directly controlling said circuit, and means by which the calling subscriber energizes said relay to maintain the continuity of the circuit during use of the same for talking purposes.

139. In a telephone system divided into groups, an automatic switch having vertical motion to select groups and rotary motion to find an idle trunk in any selected group, a talking circuit, a relay in said switch having contact springs for directly controlling said circuit, means for energizing said relay, and means by which the calling subscriber de-energizes said relay for maintaining the continuity of the circuit for talking purposes.

140. A telephone system divided into groups comprising a talking circuit, means having vertical motion to select groups and rotary motion to find an idle trunk in any selected group, a series of line-switching relays controlling said circuit, and means by which a calling subscriber successively controls said relays in the establishment of said circuit, each relay adapted by a single movement of its armature to close said circuit thereat.

141. A telephone system divided into groups comprising a talking circuit, means for extending a connection from a calling to a called subscriber's line, said means including line relays, means having vertical motion to select groups and rotary motion to find an idle trunk in any selected group, controlled by said relays, a cut-off relay adapted and operative by a single movement of its armature to cut off the line relays and close the talking circuit thereat before the call reaches the line of the called subscriber, and means by which the calling subscriber controls said cut-off relay.

142. A telephone system divided into groups comprising a talking circuit, a bridge including an electromagnetic switch-operating element across said circuit, a bridge-cut-off relay for controlling said bridge, a trunk line, automatic means for energizing said relay by the establishment of connection to said trunk line, and automatic means for de-energizing said relay in the establishment of connection from said trunk line, said system provided with elements having vertical motion to select groups and rotary motion to find the called line in any selected group.

143. A telephone system divided into groups comprising a trunk line, a line-switching relay therefor, automatic means for energizing said relay by the establishment of connection to said trunk line, and automatic means for de-energizing said relay in the establishment of connection from said trunk line, said system provided with elements having vertical motion to select groups and rotary motion to find the called line in any selected group for extending the connection from said trunk.

144. In a telephone system divided into groups, a talking circuit, means having vertical motion to select groups and rotary motion to connect with a line in any selected group, a series of relay bridges across the conductors of said talking circuit for controlling said vertical and rotary motion to extend the call, and a bridge-cut-off relay operative by a single movement to cut off one of said bridges before the call reaches the called line.

145. In a telephone system divided into groups, a talking circuit, means having vertical motion to select groups and rotary motion to connect with a line in any selected group, a plurality of relay bridges across the conductors of said talking circuit for controlling said vertical and rotary motion to extend the call, and a plurality of bridge-cut-off relays operative by a single movement to each cut off a bridge before the call reaches the called line.

146. In an automatic telephone system, a built-up circuit between two subscribers' lines, selecting switches and trunk lines involved in building up said circuit, controlling magnets connected with said circuit at some of said selecting switches, other controlling magnets disconnected from said circuit at other of said selecting switches, relays each operative by a single motion to put the said disconnected magnets back on the conductors of said circuit, and means at the switches having connected magnets for causing those switches having disconnected magnets to disconnect said built-up circuit, substantially as described.

147. An automatic telephone system comprising a temporarily established talking circuit, a selector and connector, a selector-relay-bridge temporarily disconnected or cut off from the said circuit, a relay operative by one motion to put the said bridge back on the conductors of said circuit, and a connector-relay-bridge retained across the said circuit for releasing purposes, together with selector and connector releasing means controlled by the said connector-relay-bridge.

148. In a telephone exchange system, a talking circuit, a plurality of bridges including operating elements across the conductors of said circuit for use in forming said talking circuit, cut-off relays for reducing the num-

ber of bridges during talking by a single movement of each relay, releasing means for disconnecting between subscribers, and means for retaining one or more of said bridges to control the said releasing means.

149. In a telephone exchange system, the combination of telephone lines, means including an automatic switch for trunking a calling line into connection with a called line to form a talking circuit, a bridge including a controlling magnet individual to said switch across the conductors of said circuit, before the latter is in condition for talking and a relay operative by a single motion to cut off or open up said bridge during talking.

150. In a telephone system, an automatic switch having three successive operations, a plurality of relays, and switching means controlled entirely by said relays having but two operative positions, said relays directly controlling the three successive operations of the switch.

151. In a telephone system, a plurality of lines, an automatic selecting switch for extending connection to one of said lines, means for moving said switch vertically, means for then rotating said switch, means for then extending the connection to one of said lines, a plurality of relays in said switch, and contacts directly controlled by said relays having but two operative positions, said relays directly controlling the three successive operations of said switch.

152. In a telephone system, a subscriber's line, an automatic trunk-selecting switch individual thereto, a line relay therefor, a cut-off relay, means for energizing said cut-off relay, and means controlled by the energization of said cut-off relay to open the line relay circuit and connect both sides of the line with the line wipers of said switch.

153. In a telephone system, a subscriber's line, an automatic trunk-selecting switch individual thereto, line wipers for said switch normally disconnected from said line, a line relay therefore, a cut-off relay, and means controlled by said cut-off relay for opening the line relay circuit and for connecting both sides of the line and line wipers when the switch makes a call.

154. In an automatic telephone system, a subscriber's line, a selecting switch for said line, a disconnect relay for said selecting switch, a trunk line to which said selecting switch is adapted to connect said subscriber's line, a selecting switch for said trunk line, a pair of controlling magnets bridged across said trunk line at said latter selecting switch, and a pair of contacts on said controlling magnets actuated when said magnets are simultaneously operated to close a circuit directly through the disconnect magnet of the second named selecting switch and through the disconnect relay of

said first named selecting switch, substantially as described.

155. In an automatic telephone system, a pair of subscribers' lines connected by trunk lines at a central office, automatic selecting devices for said subscribers' lines and for each of said trunk lines, a pair of controlling magnets bridged across said metallic circuit line at one only of said selecting devices, a separate conductor extending from the selecting device having bridged magnets to another of said selecting devices, a disconnect relay at said selecting device included in said separate conductor, a source of current adapted to be included in said separate conductor at the selecting switch having bridged controlling magnets, and a pair of contacts moved by said controlling magnets to close the circuit through said separate conductor to cause the release of said latter selecting switch, substantially as described.

156. In an automatic telephone system, a pair of subscribers' lines connected by trunk lines at a central office, automatic selecting devices for said subscribers' lines and for each of said trunk lines, a pair of controlling magnets bridged across said metallic circuit line at one only of said selecting devices, a separate conductor extending from the selecting device having bridged magnets to another of said selecting devices, a disconnect magnet at said selecting device included in said separate conductor, a source of current adapted to be included in said separate conductor at the selecting switch having bridged controlling magnets, and a pair of contacts moved by said controlling magnets to close the circuit through said separate conductor to cause the release of said latter selecting switch, substantially as described.

157. A telephone exchange system comprising a telephone line and associated automatic switch mechanism for service in extending the circuit of said line, said mechanism including only passive and active main contacts, said mechanism being adapted for primary and secondary adjustment, primary and secondary off-normal contacts, magnets and connected mechanism for operating said active contacts, relays, and suitable electrical connections.

158. In a telephone exchange system, the combination of a telephone line, a line relay individual to the said telephone line and adapted to be cut off from the line, a cut-off relay, a circuit for energizing said cut off relay, automatic means for closing said circuit when the line calls, controlled by the calling subscriber, another circuit for energizing the cut-off relay when the line is called.

159. In a telephone exchange system, the combination of a telephone line, a normally disconnected terminal for said line, a line

relay individual to said telephone line and adapted to be cut off from the line, a cut off relay, means for connecting the terminal with the line when the cut off relay is energized, means for disconnecting the line relay when the cut off relay is energized, automatic means for energizing the cut off relay when the line calls, controlled by the calling subscriber, and means for energizing the cut off relay when the line is called, together with means by which a calling subscriber controls said last mentioned energizing means.

160. In a telephone system, a subscriber's line, a progressively movable switch individual to said line, means for establishing a connection from or to said line, an operating magnet in said switch normally connected to said line, a cut-off relay, and means for energizing said cut-off relay to disconnect said operating magnet from the line when said line is calling or is being called.

161. In a telephone system, a subscriber's line, an automatic switch individual to said line, means including said switch for establishing a talking connection including said line as a calling line, means for extending a talking connection to said line as a called line, a line relay for said switch normally connected in bridge of said line, a cut-off relay for disconnecting said line relay, and circuits excluding any conductors involved in said talking connections for energizing said cut-off relay whenever said line is calling or is being called.

162. In a telephone system, a subscriber's line, an automatic switch individual to said line, means including said switch for completing a connection including said line as a calling line, an automatic subscriber controlled connector switch having direct access to said line for extending a connection to said line as a called line, a line relay normally connected in bridge of said line, a cut-off relay for disconnecting said line relay, and circuits for energizing said cut-off relay whenever said line is calling or is being called.

163. In a telephone exchange system, the combination of a telephone line, a normally disconnected terminal for said line, a line relay individual to said telephone and adapted to be cut off from the line, a cut-off relay, means for connecting the terminal with the line when the cut-off relay is energized, means for disconnecting the line relay when the cut-off relay is energized, automatic means for energizing the cut-off relay when the line calls, controlled by the calling subscriber, and means for energizing the cut-off relay when the line is called.

164. In a telephone system, a subscriber's line, an automatic switch individual to said line, means including said switch for extending said line when calling, means for connecting with said line as a called line, a line relay for said switch normally connected in bridge of said line, a cut-off relay for disconnecting said line relay, and circuits for maintaining said cut-off relay energized throughout the connection when said line is engaged either as a calling or as a called line.

165. In a telephone system, an automatic switch, a line terminating in said switch but normally disconnected from the wipers thereof, trunk lines accessible to the wipers of said switch, means for controlling said switch over said line to cause the switch to select an idle trunk line, a relay for connecting the line with the wipers of said switch, a circuit for said relay maintained closed during said selecting operation, and means for short circuiting said relay during the said selecting operation to prevent the energization thereof until the selecting operation is completed.

166. In an automatic switch, a motor magnet, a wiper connecting relay, a circuit including said relay and magnet in series, said magnet being non-responsive when connected in series with said relay, and a branch circuit for operating said magnet and for shunting said relay to prevent the operation thereof while the magnet is operating.

167. In an automatic switch, an operating magnet, a wiper connecting relay, and a circuit for energizing said relay in series with said magnet, the said relay and magnet having their windings so proportioned that the said magnet is not operatively energized in said circuit.

168. In an automatic switch, a line relay, a relay for cutting off said line relay, an operating magnet, and a circuit for energizing said cut-off relay in series with said magnet, the said cut-off relay and magnet having their windings so proportioned that the said magnet is not operatively energized in said circuit.

169. In an automatic switch, a line relay, a relay for cutting off said line relay, an operating magnet, a circuit including said cut off relay and said magnet in series, said magnet being non-responsive to current flow in said circuit, and a branch circuit for shunting said cut-off relay and for supplying sufficient current to said magnet to operate the same.

Signed by me at Chicago, Cook County, Illinois, this 15th day of June, 1905.

WILSON L. CAMPBELL.
